TELEPHONE SYSTEM

Thomas F. Crocker, Chicago, Ill., assignor to
 Associated Electric Laboratories, Inc., Chicago,
 Ill., a corporation of Delaware

Application December 29, 1939, Serial No. 311,551

73 Claims.

(Cl. 179—27)

The present invention relates to telephone systems and more particularly to improved arrangements for distributing calls in telephone systems of the semi-automatic type.

In a conventional telephone system of the semi-automatic type the various manual telephone lines terminate in jacks at the A and B operator positions; and an automatic switch train provided with a distributing system is interposed between the A operator positions and the B operator positions. In a telephone system of this type, calls on the telephone lines are answered directly by the operators at the A operator positions and routed by the switch train under the control of the distributing system to the B operator positions to be completed.

Accordingly in telephone systems of this type, the traffic between the A operator positions and the B operator positions is governed by the distributing system. However, the traffic between the calling telephone lines and the various A operator positions is not governed but remains under the manual control of the operators at the A operator positions, rendering the number of calls on the telephone lines answered by an operator at a given A operator position and routed therefrom to the B operator positions to be completed entirely within the discretion of the operator at the given A operator position.

Accordingly, it is an object of the present invention to provide in a telephone system of the type described, improved apparatus for distributing calls on telephone lines to a number of A operator positions to be answered.

Another object of the invention is to provide in a telephone system including a number of A operator positions and a number of B operator positions, an improved arrangement for distributing and for storing incoming calls on telephone lines to the A operator positions to be answered and recalls on established connections from the B operator positions to the A operator positions to be answered.

Another object of the invention is to provide in a telephone system including a number of operator positions, an improved arrangement for distributing and for storing incoming calls on telephone lines to the operator positions to be answered.

Another object of the invention is to provide in a telephone system including a number of operator positions provided with facilities for establishing connections between telephone lines, an improved arrangement for distributing and

storing recalls on the established connections to the operator positions to be answered.

A further object of the invention is to provide in a telephone system including an operator position, improved switching apparatus for routing a call to the operator position to be answered and for extending the call from the operator position after it has been answered.

A further object of the invention is to provide in a telephone system including an operator position, an improved switching link for establishing a connection between a calling line and a called line, which switching link is under the joint control of automatic apparatus and an operator at the operator position.

A further object of the invention is to provide in a telephone system including an operator position, an improved switching link selectively operative to establish a connection between a calling line and a called line including the operator position and to establish a direct connection between the calling line and the called line excluding the operator position, and apparatus under the control of an operator at the operator position for selectively controlling the operation of the switching link.

A further object of the invention is to provide in a telephone system including an operator position, improved apparatus at the operator position for supervising calling telephone lines in the system and establishing connections between telephone lines in the system and for performing service functions over the telephone lines in the system.

The features of the present invention are illustrated as being incorporated in a telephone system comprising an exchange terminating a plurality of manual telephone lines and including a number of A operator positions, a number of B operator positions and a number of switching links. The switching links have access to the telephone lines, to the A operator positions and to the B operator positions; while the B operator positions have access to the telephone lines. The telephone lines comprise three classes which are rendered corresponding classes of services consisting of flat rate service, call register service and prepay service.

In accordance with one feature of the invention the telephone system comprises a plurality of subscriber lines, a plurality of A operator positions, a B operator position and a storage unit. Also, the system comprises means for routing a call upon any one of the subscriber lines to an idle one of the A operator positions

to be answered when one of the A operator positions is idle, means for routing a call upon the one subscriber line to the storage unit to be stored when all of the A operator positions are busy, means for routing a call upon the one subscriber line stored in the storage unit to an idle one of the A operator positions to be answered when one of the A operator positions becomes idle, means for routing a call from the one A operator position to the B operator position, and means for establishing a connection between the one subscriber line and the B operator position independent of the one A operator position, thereby to route a call from the one subscriber line to the B operator position. Further, the system comprises means for routing a recall by the operator at the B operator position upon the established connection to an idle one of the A operator positions to be answered when one of the A operator positions is idle, means for routing a recall upon the established connection to the storage unit to be stored when all of the A operator positions are busy, and means for routing a recall upon the established connection stored in the storage unit to an idle one of the A operator positions to be answered when one of the A operator positions becomes idle.

In accordance with another feature of the invention the telephone system comprises a switching link including an answer switch having access to the telephone lines and a finder switch having access to the operator positions and to a number of storage settings provided in the storage unit, means controlled by the presence of a call on one of the telephone lines for initiating substantially simultaneous operations of the answer switch and the finder switch, means controlled when the answer switch finds a calling one of the telephone lines for arresting operation of the answer switch, thereby to extend a call from the one telephone line to the link, means controlled when the finder switch finds an idle one of the operator positions or a prepared one of the storage settings of the storage unit for arresting operation of the finder switch, thereby to extend a call from the link to the one operator position to be answered or to store a call on the link in the one storage setting of the storage unit. Also, the system comprises means for preparing the storage settings of the storage unit in a predetermined order when all of the operator positions are busy, and additional means controlled when one of the operator positions becomes idle for initiating reoperation of the finder switch.

In accordance with another object of the invention, in the telephone system, each switching link includes a first branch provided with an answer switch, a second branch provided with a call switch and a third branch provided with a finder switch having access to the operator positions and to the storage settings of the storage unit. Also, the system comprises a link distributor for assigning idle ones of the switching links for use in a predetermined order, a position distributor for assigning idle ones of the operator positions for use in a predetermined order; while each operator position includes telephone apparatus. The answer switches of assigned links are operative to seize calling telephone lines, thereby to extend the calls to the assigned links; while the finder switches of assigned links are operative to seize assigned ones of the operator positions, thereby to route the calls on the assigned links to the assigned operator positions to

be answered. Also, the finder switches are operative to seize prepared ones of the storage settings of the storage unit, thereby to store the calls on the assigned links in the storage unit. More particularly, the calls on the assigned links are routed to the operator positions to be answered in the event there are no assigned operator positions and routed to the storage unit to be stored in the event there are no assigned operator positions. Subsequently the calls on the assigned links stored in the storage settings of the storage unit are routed by the finder switches to assigned ones of the operator positions to be answered as the operator positions are assigned for use. 15 Also, the system comprises calling means at each operator position operative to cause the call switches of the assigned links to seize called telephone lines, thereby to complete connections between the calling telephone lines and the called telephone lines including the first, the second and the third branches of the assigned links and the telephone apparatus at the operator positions. 20 25 30

In accordance with a further feature of the invention, the telephone system comprises means under the joint control of any one of the calling telephone lines and an operator at any one of the operator positions to which a call on the corresponding one of the assigned links is routed for releasing the connection prior to the operation of the calling means at the one operator position, and means under the joint control of any one of the calling lines and the corresponding one of the called lines for releasing the connection subsequent to the operation of the transfer means at the one of the operator positions to which the call on the corresponding one of the assigned links was routed.

In accordance with a further object of the invention, the telephone system comprises means controlled when a call on any one of the assigned links is routed to an idle one of the operator positions or to the storage unit for preventing the release of the one assigned link, and means under the control of an operator at any one of the operator positions to which the call on any one of the assigned links is routed for releasing the assigned link.

In accordance with a further feature of the invention the telephone system comprises a storage unit of limited storage capacity and a conservator of unlimited conservation capacity. The switching links are operative to route calls to the operator positions to be answered when the operator positions are idle, to route calls to the storage unit to be stored when all of the operator positions are busy, and to route calls to the conservator to be conserved when the storage capacity of the storage unit is exhausted. Also, the switching links are operative to route calls stored in the storage unit to the operator positions to be answered when the operator positions become idle, and to route calls conserved in the conservator to the storage unit to be stored when the storage capacity of the storage unit is replenished.

In accordance with a further feature of the invention, in the telephone system, the finder

switch of each link is provided with a number of first settings individually corresponding to the operator positions and a second number of settings individually corresponding to the storage settings of the storage unit. Also, the system comprises means controlled when all of the operator positions are busy for causing the finder switches having calls thereon to be operated to different ones of the second settings, thereby to store the calls on the finder switches in the different storage settings of the storage unit, means controlled when there are no calls on the finder switches stored on the storage unit for causing the finder switches having calls thereon to be operated to different ones of the first settings corresponding to idle ones of the operator positions, thereby to route the calls on the finder switches to the operator positions to be answered, and means controlled when there are calls on the finder switches stored in the storage settings of the storage unit for causing the finder switches to be reoperated from the different ones of the second settings to different ones of the first settings corresponding to idle ones of the operator positions, thereby to route the calls stored in the different storage settings of the storage unit to idle ones of the operator positions to be answered. Further, the system comprises a storage distributor governed in accordance with the different ones of the second settings of the finder switches for controlling the order of reoperation of the finder switches, whereby the calls on the finder switches are routed to the operator positions to be answered in the same order that the calls on the finder switches are routed to the different storage settings of the storage unit to be stored.

Further features of the invention pertain to the particular arrangement of the circuit elements thereof, whereby the above-outlined and additional operating features are attained.

The novel features believed to be characteristic of the invention are set forth with particularity in the appended claims. The invention, both as to its organization and method of operation, together with further objects and advantages thereof, will best be understood by reference to the following specification taken in connection with the accompanying drawings in which Figure 1 illustrates the general arrangement of a telephone system including a local exchange and a distant exchange embodying the present invention; and Figs. 2 to 6, inclusive, taken together, illustrate the details of a system having incorporated therein the features of the invention, as briefly outlined above.

DESCRIPTION OF THE APPARATUS INCORPORATED IN THE TELEPHONE SYSTEM

Referring now more particularly to Fig. 1 of the drawings the telephone system there illustrated comprises a local exchange 20, a distant exchange 30 and a plurality of one-way trunk lines, including the trunk line 470, extending therebetween. The local exchange 20 and the distant exchange 30 are of the manual type, each serving a number of groups of telephone stations to which different classes of service are rendered. For example, the local exchange 20 serves a group of subscriber substations, including the subscriber substation T1, which is rendered flat rate service; a group of party subscriber substations, including the party subscriber substations T2 and T3, which is rendered call register service; and a group of paystations,

including the paystation T4, which is rendered prepay service. A telephone line having a line circuit individually associated therewith extends to each telephone station in the local exchange; the telephone lines 225, 270 and 285 respectively extending to the subscriber substation T1, the party subscriber substations T2 and T3, and the paystation T4. The flat rate line circuit 200 is individually associated with the telephone line 225; the two-party line register circuit 240 is individually associated with the telephone line 270; and the prepay manual line circuit 280 is individually associated with the telephone line 285. Each of the subscriber substations and paystations in the local exchange 20 is provided with station equipment, including a telephone instrument and a ringer.

Also, the local exchange 20 comprises a number of A operator positions, including the first A operator position 500, a number of B operator positions, including the first B operator position 494, and a number of toll operator positions, including the toll operator position 499. Each A operator position has a trunk individually extending thereto, the trunk 520 individually extending to the first A operator position 500; each B operator position has a group of trunks individually extending thereto, the trunk 490 being included in the group of trunks individually extending to the first B operator position 494; and each toll operator position has a group of trunks individually extending thereto, the trunk 495 being included in the group of trunks individually extending to the toll operator position 499. Each trunk extending to each B operator position is provided with a trunk line circuit individual thereto, the trunk line circuit 480 being individual to the trunk 490 extending to the first B operator position 494. Each trunk extending to each toll operator position is provided with a trunk line circuit individual thereto, the trunk line circuit 497 being individual to the trunk 495 extending to the toll operator position 499. Also each trunk line extending between the local exchange 20 and a B operator position 498 in the distant exchange 30 is provided with a trunk line circuit individual thereto, the trunk line circuit 472 being individual to the trunk line 470 extending between the local exchange 20 and the B operator position 498 in the distant exchange 30.

Further the local exchange 20 comprises a number of finder-selector links, including the finder-selector link illustrated, and a distributor 501 for assigning idle ones of the links to the use of the telephone stations. For example, the link illustrated includes a finder switch 300 and a selector switch 400. Also a sequence switch is individually associated with each of the links, the sequence switch 380 being individually associated with the link illustrated. Finally the local exchange 20 comprises an A operator position distributor 630 for assigning idle ones of the A operator positions to receive incoming calls to the local exchange and a call storage unit 600.

Each of the finder switches, such, for example, as the finder switch 300, constitutes an answer switch having access to each of the telephone lines in the local exchange; each of the selector switches, such, for example, as the selector switch 400, constitutes a call switch having access to each of the trunks extending to the B operator positions and to the toll operator positions and to each of the trunk lines extending to the distant exchange 30; and each of the sequence switches,

such, for example, as the sequence switch 380, constitutes a position and storage finder switch having access to each of the trunks individually extending to the A operator positions and to the call storage unit 600. Also it is noted that each B operator position in the local exchange 20 has access to each telephone line therein.

The distant exchange 30 comprises a number of A operator positions, not shown, and a number of B operator positions, including the B operator position 498. It is noted that the trunk line 470 extending between the local exchange 20 and the distant exchange 30 is terminated at the B operator position 498 in the distant exchange 30.

Preferably, each of the finder-selector links is 15 identical to the link illustrated which comprises a finder switch 300 and a selector switch 400, as previously noted. The finder switch 300, as best shown in Fig. 3, comprises a switching mechanism 310 of the 200-point Strowger type including a carriage provided with a first wiper set, including the wipers 311, 312 and 313, a second wiper set, including the wipers 314, 315, 316 and 317, and a control wiper 318. It is noted that the wipers 311, 312 and 313 of the first wiper set and the wipers 314, 315, 316 and 317 of the second wiper set are capable of both vertical and rotary movements; while the control wiper 318 is capable of vertical movement. Further the mechanism 310 comprises a circumferentially disposed 30 main contact bank provided with two sections respectively associated with the first and second wiper sets and a vertical control contact bank associated with the control wiper 318. Accordingly, in the mechanism 310, the first and second wiper sets respectively have access to first and second groups of one hundred lines each, respectively terminated by the first and second sections of the main contact bank. Also, the mechanism 310 is provided with a vertical magnet M365 for moving the first and second wiper sets thereof in the vertical direction, a rotary magnet M367 for moving the first and second wiper sets thereof in the rotary direction and a release magnet M369 for releasing the first and second wiper sets 45 thereof and for causing these wiper sets to be returned to their normal positions. Finally the mechanism 310 has three sets of switch springs S370, S371 and S372 operatively associated therewith which are controlled in accordance with the movements of the first and second wiper sets thereof, in a manner more fully described subsequently.

Also, the finder switch 300 comprises a number of relays, including two switching relays R320 and R330, a start relay R340 and a cut-in relay R350 connected and arranged in a manner more fully described subsequently.

The selector switch 400, as best shown in Fig. 4, comprises a switching mechanism 410 of the 100-point Strowger type including a carriage provided with a wiper set including the wipers 411, 412 and 413. It is noted that the wipers 411, 412 and 413 of the wiper set are capable of both vertical and rotary movements. Further the mechanism 410 comprises a circumferentially disposed main contact bank associated with the wiper set. Accordingly, the wiper set has access to a group of one hundred lines terminated by the main contact bank. Also the mechanism 410 is provided with a vertical magnet M414 for moving the wiper set thereof in the vertical direction, a rotary magnet M416 for moving the wiper set thereof in the rotary direction and a release magnet M418 for releasing the wiper set thereof and for causing 75

the wiper set to be returned to its normal position. Finally the mechanism 410 has a number of switch springs S419, S420, S421 and S422 operatively associated therewith which are controlled in accordance with the movements of the wiper set thereof in a manner more fully described subsequently.

Also the selector switch 400 comprises a number of relays including a lockout relay R425, a battery supply relay R430, a control relay R440, a call back relay R445, an error relay R450, a line relay R455, a hold relay R460, a transfer relay R465 and a switching relay R470 connected and arranged in a manner more fully described subsequently.

Preferably, each of the sequence switches is identical to the sequence switch 380 individually associated with the link illustrated. The sequence switch 380 is of the rotary type and comprises, as shown in Fig. 3, six rotary wipers 381, 383, 385, 387, 389 and 391 provided with individually associated rotary contact banks 382, 384, 386, 388, 390 and 392. Also the sequence switch 380 is provided with a rotary magnet M393 for moving the wipers noted in the rotary direction.

The distributor 301 illustrated in Fig. 3 has access to each of the links in the local exchange 20 and is operative to assign an idle one of the links to the use of any one of the telephone stations in the local exchange. The details of the connection and arrangement of the distributor 301 are not disclosed as they form no part of the present invention. However, for reference purpose it is noted that the connection and arrangement of a distributor of the type of the distributor 301 is shown in the copending application of Edward S. Peterson, Serial No. 233,021, filed October 3, 1938. Also a marking network 305, shown in Fig. 3, is associated with the distributor 301 in order to initiate operation thereof when a call is initiated on one of the telephone lines extending to a telephone station in the local exchange 20.

Preferably, each of the flat rate line circuits is identical to the flat rate line circuit 200 individually associated with the telephone line 225 extending to the subscriber substation T1, shown in Fig. 2, which comprises a line and cutoff relay R210 and a busy relay R220 connected and arranged in a manner more fully described subsequently. Further it is noted that a tone transformer 216 is commonly associated with each of the flat rate line circuits.

Preferably, each of the two-party line register circuits is identical to the two-party line register circuit 240 individually associated with the telephone line 270 extending to the party subscriber substations T2 and T3, shown in Fig. 2, which comprises a line and cutoff relay R260, a lockout relay R250, a control relay R245 and two registers respectively provided with register magnets M241 and M242, and connected and arranged in a manner more fully described subsequently. Also a signal lamp L243 is individually associated with the two-party line register circuit 240.

Preferably each of the prepay manual line circuits is identical to the prepay manual line circuit 280 individually associated with the telephone line 285 extending to the paystation T4, shown in Fig. 2. The prepay manual line circuit 280 comprises a line circuit of any known connection and arrangement; the details of the connection and arrangement of the line circuit 280 are not disclosed as they form no part of the present invention.

Preferably each of the trunk line circuits is identical to the trunk line circuit 480 individually associated with the trunk 490 extending to the first B operator position 494, shown in Fig. 4, which comprises a line relay R480 and a busy relay R485 connected and arranged in a manner more fully described subsequently.

Preferably each of the B operator positions in the local exchange 20 is identical to the first B operator position 494, shown in Figs. 4 and 2. 10 The first B operator position 494 comprises conventional answering equipment, not shown; conventional calling equipment including a number of call jacks J201, J202 and J203 respectively terminating the telephone lines 225, 270 and 285; and a number of conventional cord circuits, not shown.

Preferably each of the A operator positions is identical to the first A operator position 500, shown in Figs. 5 and 6, which comprises a trunk circuit provided with a set of position keys including an error release key K550, a permanent lockout release key K555, a reverting call key K570, a split key K575, a coin collect key K580, a coin return key K585, a first register key K588, a second register key K590, a transfer key K586 and a control key K560. Also the trunk circuit at the first A operator position 500 comprises a telephone instrument including a transmitter 508 and a receiver 507, a repeater 501, an impedance element 1558, a key sender K520 and a number of relays including three tone relays R515, R520 and R525, a rear split relay R530, a front split relay R535, an impulse relay R540 and two signal relays R685 and R690. Also associated with the first A operator position 500 are a peg count meter provided with a register magnet M547 and three signal lamps including a flat rate signal lamp L680, a message register signal lamp L681 and a prepay signal lamp L682. The key sender K520 is of a well-known type; accordingly, the details of the connection and arrangement thereof are not disclosed as they form no part of the present invention.

The call storage unit 600, shown in Fig. 6, comprises six marking relays 1M to 6M, inclusive, a control relay R610 and a release relay R620, connected and arranged in a manner more fully described subsequently. Also six storage lamps L601 to L606, inclusive, are associated with the call storage unit 600 and commonly associated with each of the A operator positions.

The A operator position distributor 630, shown in Fig. 6, comprises a number of hold relays R630, R640, R645, etc., respectively corresponding to the A operator positions; a number of position relays R650, R660, R665, etc., respectively corresponding to the A operator positions; and a control relay R670 connected and arranged in a manner more fully described subsequently.

A better understanding of the connection and arrangement of the apparatus incorporated in the telephone system will be facilitated from a consideration of the detailed operation of the various pieces of apparatus incorporated therein incident to the completion and the handling of the various calls at the first A operator position 500, as will appear hereinafter.

GENERAL OPERATION OF THE SYSTEM

Considering now the general operation of the system with reference to Fig. 1 of the drawings, it is noted that when a call is initiated at any one of the subscriber substations or at any one of the paystations in the local exchange 20 the

line circuit individually associated with the telephone line extending thereto is controlled, thereby to initiate operation of the distributor 301. The distributor 301 is of the preselective type and operates to select an idle one of the links when a previously selected link is assigned to the use of a calling telephone station. Accordingly the distributor 301 operates at this time in order to assign a previously selected one of the links, such, for example, as the link illustrated, to the use of the calling telephone station; whereupon the finder switch 300 operates to seize the telephone line extending to the calling telephone station, and operation of the sequence switch 380 individually associated with the link illustrated is initiated. When the finder switch 300 seizes the telephone line extending to the calling telephone station the distributor 301 is released and operates to preselect another idle link, as previously noted.

The A operator position distributor 630 pre-selects an idle one of the A operator positions for use, and when a preselected one of the A operator positions is taken for use the A operator position distributor 630 operates to preselect another idle one of the A operator positions for use. Upon operating the sequence switch 380 seizes the trunk extending to the previously selected A operator position, thereby to extend the call from the calling telephone station to the selected A operator position. The operator at the selected A operator position answers the call and then operates the key sender at her position, thereby to control the operation of the selector switch 400 in order to extend the call to its destination. In this connection it is noted that the selector switch 400 may be selectively controlled to extend the call to any idle B operator position in the local exchange 20, to any idle toll operator position in the local exchange 20 or to the B operator position 498 in the distant exchange 30.

In the event the call is to be routed to a telephone station in the local exchange 20 the selector switch 400 is controlled in order to route the call to an idle B operator position in the local exchange 20. The operator at the idle B operator position in the local exchange 20 answers the call and then extends the call to the called telephone station in the local exchange 20, in the usual manner. In the event the call is to be routed to a telephone station in the distant exchange 30 the selector switch 400 is controlled in order to route the call to the B operator position 498 in the distant exchange 30. The operator at the B operator position 498 in the distant exchange 30 answers the call and then extends the call to the called telephone station in the distant exchange 30, in the usual manner. In the event the call is to be routed toll the selector switch 400 is controlled in order to route the call to an idle one of the toll operator positions in the local exchange 20. The operator at the idle toll operator position in the local exchange 20 answers the call and then routes the call toll in the usual manner.

After the call has been routed from the idle A operator position in the local exchange 20 to an idle one of the B operator positions in the local exchange 20, to an idle one of the toll operator positions in the local exchange 20 or to the B operator position 498 in the distant exchange 30 and the information concerning the extension of the call has been conveyed to the called operator, the operator at the idle A operator position re-

leases the connection between her position and the finder switch 300 and the selector switch 400, whereupon a direct connection is completed between the finder switch 300 and the selector switch 400, excluding the A operator position.

It is noted that the called operator to which the call is routed by the selector switch 400 may recall the operator at an idle one of the A operator positions in the local exchange 20 by causing the sequence switch 380 individually associated with the link illustrated to seize the trunk extending to the idle A operator position under the control of the A operator position distributor 300, in the manner previously explained.

In the event all of the A operator positions in the local exchange 20 are busy when operation of the sequence switch 380 is initiated, the sequence switch 380 seizes the call storage unit 600. More particularly, the sequence switches individually associated with the links in the local exchange 20 seize the respective positions of the call storage unit 600 in a predetermined order, thereby to cause the calls and recalls to be stored in the call storage unit 600 in a predetermined order when all of the A operator positions in the local exchange 20 are busy. At this time, when a number of calls and recalls on a number of the links are stored in the call storage unit 600 and one of the A operator positions in the local exchange 20 becomes idle the A operator position distributor 300 operates to assign the idle A operator position for use and causes the call storage unit 600 to initiate operation of the sequence switch corresponding to the first stored call or recall in the call storage unit 600. The sequence switch corresponding to the first stored call or recall in the call storage unit 600 then operates to find the assigned A operator position. The call storage unit 600 then operates to cause each of the remainder of the sequence switches to be advanced one position, thereby to advance by one position the calls and recalls stored in the call storage unit 600. Accordingly the call storage unit 600 operates to cause incoming calls and recalls to be stored in a predetermined order when all of the A operator positions in the local exchange 20 are busy; and causes the stored calls and recalls to be released to be answered at the A operator positions in the same predetermined order as the A operator positions in the local exchange 20 become idle.

After a call from a calling telephone station has been extended from one of the A operator positions to one of the B operator positions in either the local exchange 20 or the distant exchange 30 or to one of the toll operator positions in the local exchange 20, the release of the established connection is under the joint control of the calling telephone station and the called operator position.

Flat rate subscriber substation call

A call from a flat rate subscriber substation, such, for example, as the subscriber substation T1, is initiated by removing the receiver of the telephone instrument thereat from its switchhook. When the receiver of the telephone instrument at the subscriber substation T1 is removed from its switchhook, a bridge path is completed between the line conductors C226 and C227 of the telephone line 225 extending to the subscriber substation T1. When this bridge path is completed between the line conductor of the telephone line 225 a circuit is completed for energizing in series the windings of the line and cut-

off relay R210. This circuit extends from ground by way of the lower winding of R210, the contacts 212, C227, the bridge path between the line conductors C227 and C226, C226, the contacts 211 and the upper and intermediate windings of R210 to battery. When energized over the above-traced circuit the line and cutoff relay R210 operates partially, thereby to complete, at the contacts 214, a path for applying ground potential to the start conductor C230 and to complete, at the contacts 213, an obvious connection between the control conductors C228 and C229 of the telephone line 225. The path for applying ground potential to the start conductor C230 extends from ground by way of the contacts 221, 215 and 214 to the start conductor C230. The application of ground potential to the start conductor C230 completes an obvious path for applying ground potential by way of the resistor 304 of the marking network 305 to the start conductor C308 extending to the distributor 301, and completes an obvious path for applying direct ground potential to the first contacts in the vertical control contact banks of the finder switches. The application of ground potential to the start conductor C308 initiates operation of the distributor 301 and the application of direct ground potential to the first contacts in the vertical control contact banks of the finder switches marks the telephone line 225 as terminating in the first level of the main contact banks of the finder switches.

The distributor 301 is of the preselective type and operates to select another idle link as soon as the finder switch of a previously selected link 35 operates to find a calling telephone line after it has been taken for use. Assuming that the distributor 301 has previously selected the link illustrated to be taken for use at this time, the distributor 301 operates to cause ground potential to be applied to the start conductor C302, thereby to complete an obvious circuit for energizing the winding of the start relay R340. The start relay R340 then operates to interrupt, at the contacts 348, a point in a multiple path for applying ground potential to the all-link-busy conductor C308 and to complete, at the contacts 342, an obvious path for applying ground potential to the control conductor C363 of the trunk 360. The previously mentioned path for applying ground potential to the all-link-busy conductor C309 in the finder switch 300 extends, when completed, from ground by way of the contacts 348 and the set of switch springs S372 to the all-link-busy conductor C308. Also the start relay R340 completes, at the contacts 343, obvious multiple circuits for energizing the lower windings of the switching relays R320 and R330, thereby to render each of these switching relays extremely fast to operate in the event the upper winding thereof is energized. Further the start relay R340 prepares, at the contacts 347, a circuit traced hereinafter for energizing the vertical magnet M365 and prepares, at the contacts 346, a circuit traced hereinafter for energizing the rotary magnet M367.

The distributor 301 then operates to cause ground potential to be applied to the vertical conductor C305, thereby to complete the previously mentioned circuit for energizing the vertical magnet M365, this circuit extending from the grounded vertical conductor C305 by way of the contacts 347 and M365 to battery. When energized over the above-traced circuit the vertical magnet M365 operates to drive the first and second wiper sets of the mechanism 310 one step

in the vertical direction and to complete, at the contacts 366, an obvious path for applying ground potential to the interrupter conductor C306. The application of ground potential to the interrupter conductor C306 causes the distributor 301 to interrupt the application of ground potential to the vertical conductor C305; whereupon the vertical magnet M365 restores to interrupt, at the contacts 366, the previously mentioned path for applying ground potential to the interrupter conductor C306. Accordingly the vertical magnet M365 operates intermittently, thereby to drive the first and second wiper sets of the mechanism 310 step by step in the vertical direction until the control wiper 318 engages a contact in the associated vertical contact bank having direct ground potential thereon; whereupon an obvious path is completed for applying ground potential to the test conductor C307 extending to the distributor 301. In the present instance the first and second wiper sets of the mechanism 310 are driven only one step in the vertical direction; whereupon the vertical control wiper 318 engages the first contact in the associated vertical control contact bank having ground potential thereon. The application of ground potential to the test conductor C307 causes the distributor 301 to operate, thereby to interrupt the application of ground potential to the vertical conductor C305 and to apply ground potential to the rotary conductor C304. The application of ground potential to the rotary conductor C304 completes the previously mentioned circuit for energizing the rotary magnet M367, this circuit extending from the grounded rotary conductor C304 by way of the contacts 346, 330 and 328 and M367 to battery. When energized over the above-traced circuit the rotary magnet M367 operates to drive the first and second wiper sets of the mechanism 310 one step in the rotary direction and to complete, at the contacts 368, an obvious path for applying ground potential to the interrupter conductor C306. This application of ground potential to the interrupter conductor C306 causes the distributor 301 to remove the application of ground potential to the rotary conductor C304, whereupon the rotary magnet M367 restores to interrupt, at the contacts 368, the previously mentioned path for applying ground potential to the interrupter conductor C306. Accordingly the rotary magnet M367 operates intermittently, thereby to drive the first and second wiper sets of the mechanism 310 step by step in the rotary direction until either the control wiper 313 or the control wiper 317 of the respective first and second wiper sets engages the control conductor of a calling telephone line having battery potential thereon. In the present example the telephone line 225 is included in the first section of the main contact bank of the mechanism 310.

Accordingly, when the control wiper 313 of the first wiper set of the mechanism 310 engages the contact of the contact set in the first section of the main contact bank of the mechanism 310 terminating the control conductor C228 of the telephone line 225, a circuit is completed for energizing the upper winding of the switching relay R320. This circuit extends from ground by way of the contacts 221, 215 and 214, the start conductor C230, the control wiper 318, the upper winding of R320, the control wiper 313, the control conductor C228 of the telephone line 225, the contacts 213 and the intermediate winding of R210 to battery. When energized over the above-traced circuit the switching relay R320 op-

erates exceedingly fast, thereby to complete, at the contacts 328, a holding circuit for energizing the intermediate winding thereof, this circuit extending from the grounded control conductor C363 of the trunk 360 by way of the contacts 336 and 325 and the intermediate winding of R320 to battery. Also, upon operating, the switching relay R320 interrupts, at the contacts 328, a point in the previously traced circuit for energizing the rotary magnet M367, thereby positively to arrest further operation of the mechanism 310. Further the switching relay R320 interrupts, at the contacts 326, a point in a circuit traced hereinafter for energizing the upper winding of the switching relay R330, thereby positively to prevent operation of the latter relay at this time. Also the switching relay R320 interrupts, at the contacts 321, a point in a circuit traced hereinafter for energizing the release magnet M369 and completes, at the contacts 321, a connection between the rotary conductor C304 and the guard conductor C303, this connection extending from the rotary conductor C304 by way of the contacts 346, 330, 327 and 344 to the guard conductor C303. When the rotary conductor C304 is connected to the guard conductor C303 operation of the distributor 301 to control the finder switch 300 is arrested, whereupon the distributor 301 operates automatically to select for use another idle one of the links.

Also it is noted that when the carriage of the mechanism 310 is driven one step in the vertical direction the sets of switch springs S310, S311 and S312 are actuated. More particularly, the set of switch springs S310 is actuated into engagement, thereby to prepare a further point in the previously mentioned circuit for energizing the release magnet M369; while the set of switch springs S312 is actuated into disengagement, thereby to interrupt a further point in the previously traced path for applying ground potential to the all-link-busy conductor C309. Finally the contacts 372 of the set of switch springs S311 are actuated into engagement, thereby to prepare a path traced hereinafter for applying ground potential to the guard conductor C303. Finally, upon operating the switching relay R320 completes, at the contacts 322, 323 and 324, connections between the conductors of the trunk 360 extending between the finder switch 300 and the selector switch 400 and the first wiper set of the mechanism 310. More particularly, a low resistance circuit is completed, at the contacts 324, for energizing the intermediate winding of the line and cutoff relay R210, this circuit extending from the grounded control conductor C363 of the trunk 360 by way of the contacts 336 and 324, the wiper 313, the control conductor C228 of the telephone line 225, the contacts 213 and the intermediate winding of R210 to battery. When the intermediate winding of the line and cutoff relay R210 is thus energized this relay operates completely, thereby to interrupt, at the contacts 215, the previously traced path for applying ground potential to the start conductor C230 extending to the marking network 305 in order to arrest operation of the distributor 301. Further the line and cutoff relay R210 interrupts, at the contacts 211 and 212, the previously traced circuit for energizing the windings thereof across the line conductors C226 and C227 of the telephone line 225, thereby to clear the telephone line 225 of impedance elements. At this time ground potential appearing upon the control conductor C228 of the telephone line 225 is ap-

plied to the control conductor C228 thereof, thereby to mark the telephone line 225 as busy to the B operator positions in the local exchange 20.

Further it is noted that the distributor 301 operates in order to select another idle link for use only in the event ground potential appears upon the all-link-busy conductor C309 in at least one of the finder switches, ground potential being removed from the all-link-busy conductor C309 in the finder switch 300 at this time due to the operated condition of the set of switch springs S372, as previously noted. Also ground potential is applied to the guard conductor C303 in the finder switch 300, thereby to prevent the distributor 301 from preselecting the link illustrated at this time due to the busy condition of the finder switch 300. The path for applying ground potential in the finder switch 300 to the guard conductor C303 extends from ground by way of the contacts 372 of the set of switch springs S371 and the contacts 345 to the guard conductor C303, the start relay R340 being restored at this time. Further it is noted that the start relay R340 is of the slow-to-release type and restores shortly after the distributor 301 is released. Upon restoring the start relay R340 interrupts, at the contacts 342, the previously traced path for applying ground potential to the control conductor C363 of the trunk 360, ground potential being applied to the control conductor C363 of the trunk 360 in the selector switch 400 at this time. Further the start relay R340 interrupts, at the contacts 343, the previously mentioned multiple circuit for energizing the lower windings of the switching relays R320 and R330, the switching relay R320 being retained in its operated position at this time due to the completed holding circuit for energizing the intermediate winding thereof.

When the trunk 360 is connected to the telephone line 225 a loop circuit is completed for energizing in series the upper and lower windings of the error relay R450 and the upper and lower windings of the line relay R455 in the selector switch 400. This circuit extends from ground by way of the lower winding of R455, the lower winding of R450, the line conductor C362 of the trunk 360, the contacts 356, 334 and 323 and the wiper 312 to the line conductor C227 of the telephone line 225, and from battery by way of the upper winding of R455, the upper winding of R450, the line conductor C361 of the trunk 360, the contacts 353, 332 and 322 and the wiper 311 to the line conductor C226 of the telephone line 225, the line conductors C226 and C227 of the telephone line 225 being connected together by way of a bridge path at the subscriber substation T1. When the upper and lower windings of the error relay R450 are thus energized this relay remains in its restored position, this relay being of the differential type. On the other hand, when the upper and lower windings of the line relay R455 are thus energized this relay operates to complete, at the contacts 456, a circuit for energizing the winding of the hold relay R460, this circuit extending from ground by way of the contacts 475 and 456 and the winding of R460 to battery. When thus energized the hold relay R460 operates to complete, at the contacts 462, an obvious multiple circuit for applying ground potential to the control conductor C363 of the trunk 360, as previously noted. Also the hold relay R460 completes, at the contacts 463, an obvious circuit for energizing the lower wind-

ing of the switching relay R470, thereby to render the switching relay R470 exceedingly fast to operate when the upper winding thereof is energized. Further the hold relay R460 prepares, at the contacts 461, a circuit traced hereinafter for energizing the upper winding of the switching relay R470 and prepares, at the contacts 464, a circuit traced hereinafter for energizing in multiple the lower winding of the transfer relay R465 and the vertical magnet M414.

When ground potential is applied to the control conductor C363 a circuit is completed for energizing the upper winding of the transfer relay R465, this circuit extending from the grounded control conductor C363 of the trunk 360 by way of the contacts 427 and 454, the set of switch springs S420 and the upper winding of R465 to battery. When thus energized the transfer relay R465 operates to prepare, at the contacts 467, a further point in the previously mentioned multiple circuit for energizing the lower winding thereof and the vertical magnet M414 and to interrupt, at the contacts 469, a point in a circuit traced hereinafter for energizing the rotary magnet M416. Finally, upon operating the transfer relay R465 completes, at the contacts 466, an obvious path for applying ground potential to the control conductor C364 of the trunk 360. This application of ground potential to the control conductor C364 of the trunk 360 completes an obvious circuit for energizing the intermediate winding of the cutin relay R350, thereby to render the cutin relay R350 exceedingly fast to operate when the upper winding thereof is energized. Also the application of ground potential to the control conductor C364 of the trunk 360 prepares a circuit traced hereinafter for energizing the upper winding of the cutin relay R350 and completes a circuit for energizing the rotary magnet M393 of the sequence switch 380. The circuit for energizing the rotary magnet M393 of the sequence switch 380 extends from the grounded control conductor C364 of the trunk 360 by way of the contacts 350 and 394 and M393 to battery. When thus energized the rotary magnet M393 operates to condition the wipers noted of the sequence switch 380 to be driven one step in the clockwise direction and to interrupt, at the contacts 394, the previously traced circuit for energizing the rotary magnet M393; whereupon the rotary magnet M393 restores to drive the wipers noted of the sequence switch 380 one step in the clockwise direction and to recomplete, at the contacts 394, the previously traced circuit for energizing the rotary magnet M393. Accordingly the rotary magnet M393 operates intermittently, thereby to drive the wipers noted of the sequence switch 380 step by step in the clockwise direction until the cutin relay R350 is operated in a manner more fully described hereinafter to interrupt, at the contacts 350, the previously traced circuit for energizing the rotary magnet M393.

At this point it is noted that immediately the distributor 301 assigns the link illustrated to the use of the calling subscriber substation T1, the operations of the finder switch 300 and the selector switch 400 previously described are initiated and that the operation of the selector switch 400 initiates operation of the sequence switch 380 individually associated with the link illustrated. Accordingly, operation of the sequence switch 380 to find an assigned one of the A operator positions or to find a storage position in the call storage unit 600 is initiated prior to the

seizure of the telephone line 225 extending to the calling subscriber substation T1 by the finder switch 300.

Prior to continuing with the operation of the sequence switch 380 it is noted that the A operator position distributor 630 is operative to pre-select an idle one of the A operator positions to be seized by the sequence switch 380. Assuming that the first A operator position 500 has been preselected by the A operator position distributor 630 to be seized by the sequence switch 380 at this time, a holding circuit is completed for energizing in series the winding of the control relay R670 and the right-hand winding of the position relay R650, the position relay R650 corresponding to the first A operator position 500. This circuit extends from ground by way of the winding of R670, the contacts 662 and 653 and the right-hand winding of R650 to battery. The operated position relay R650 retains interrupted, at the contacts 654, a holding circuit traced hereinafter for energizing the winding of the control relay R670 in series with the right-hand winding of the position relay R665 and completes, at the contacts 652, a path for applying ground potential to the control conductor C672. The path for applying ground potential to the control conductor C672 extends from ground by way of the contacts 636 and 652 to the control conductor C672. Finally the operated position relay R650 retains prepared, at the contacts 651, a point in a circuit traced hereinafter for energizing the left-hand winding of the position relay R660 corresponding to the second A operator position. Further it is noted that no potential whatever appears upon the marking conductors C530 to C535, inclusive; while battery potential appears upon the marking conductor C536. The path for applying battery potential to the marking conductor C536 extends from battery by way of the winding of the marking relay 1M and the contacts 621 to the marking conductor C536.

Continuing now with the operation of the sequence switch 380 the rotary magnet M393 continues to operate intermittently in order to drive the wipers noted of the sequence switch 380 step by step in the clockwise direction until the wiper 391 engages the seventh contact in the associated contact bank 392 terminating the marking conductor C536; whereupon a circuit is completed for energizing in series the upper winding of the cutin relay R350 and the winding of the marking relay 1M. This circuit extends from the grounded control conductor C364 of the trunk 360 by way of the upper winding of R350, C326, the wiper 391 and engaged seventh contact in the associated contact bank 392 of the sequence switch 380, the marking conductor C536, the contacts 621 and the winding of 1M to battery. When the upper winding of the cutin relay R350 is thus energized this relay operates exceedingly fast to interrupt, at the contacts 350, the previously traced circuit for energizing the rotary magnet M393, thereby positively to arrest further operation of the sequence switch 380. Further the cutin relay R350 completes, at the contacts 358 and 359, an obvious circuit for energizing the lower winding thereof, thereby to render the cutin relay R350 exceedingly fast to restore when the previously traced circuit for energizing the upper winding thereof is interrupted.

When the winding of the marking relay 1M is thus energized it operates to complete, at the contacts 1M2, a circuit for energizing in series

the winding of the release relay R620 and the winding of the control relay R610, this circuit extending from the grounded control conductor C672 by way of the contacts 1M2, the winding of R620 and the winding of R610 to battery. When the above-traced series circuit is completed the release relay R620 operates immediately. However, the control relay R610 operates shortly thereafter, the latter relay being of the slow-to-operate type. Upon operating the release relay R620 completes, at the contacts 621', an obvious holding circuit for energizing in series the winding of the release relay R620 and the winding of the control relay R610 including the control conductor C672. Also, the release relay R620 completes, at the contacts 622, a path for applying battery potential to the control conductor C526 of the trunk 520 extending to the first A operator position 500, this path extending from battery by way of the resistor 612, the contacts 622, C674, the contacts 634, the winding of the hold relay R630 and C527 to the control conductor C526 of the trunk 520. It is noted that the control conductor C526 of the trunk 520 extending to the first A operator position 500 is terminated by the eighth contact in the contact bank 392 associated with the wiper 391 of the sequence switch 380.

Finally, upon operating the release relay R620 interrupts, at the contacts 621, the previously traced series circuit for energizing the winding of the marking relay 1M and the upper winding of the cutin relay R350, thereby to cause the marking relay 1M to restore and to cause the cutin relay R350 to restore exceedingly fast. Upon restoring the cutin relay R350 recompletes, at the contacts 350, the previously traced circuit for energizing the rotary magnet M393 of the sequence switch 380, thereby to cause the rotary magnet M393 again to operate intermittently. In the present instance the rotary magnet M393 operates and restores only once; whereupon the wiper 391 engages the eighth contact in the associated contact bank 392 of the sequence switch 380, thereby to complete a series circuit for energizing the upper winding of the cutin relay R350 and the winding of the hold relay R630. This circuit extends from the grounded control conductor C364 of the trunk 360 by way of the upper winding of R350, C326, the wiper 391 and engaged eighth contact in the associated contact bank 392 of the sequence switch 380, the control conductor C526 of the trunk 520, C527, the winding of R630, the contacts 634, C674, the contacts 622 and the resistor 612 to battery. When this series circuit is completed the cutin relay R350 again operates and the hold relay R630 operates. Upon operating the cutin relay R350 completes, at the contacts 358 and 359, the previously mentioned circuit for energizing the lower winding thereof, thereby to render the cutin relay R350 exceedingly fast to restore when the previously traced circuit for energizing the upper winding thereof is interrupted. Further the cutin relay R350 interrupts, at the contacts 350, the previously traced circuit for energizing the rotary magnet M393, thereby positively to arrest further operation of the sequence switch 380. Accordingly, at this time the wipers noted of the sequence switch 380 engage the contacts in the associated contact banks thereof terminating the conductors of the trunk 520 extending to the first A operator position 500.

Upon operating, the hold relay R630 completes, at the contacts 632 and 633, an alternative hold-

ing circuit for energizing in series the winding of the hold relay R630 and the upper winding of the cutin relay R350, this circuit extending from battery by way of the resistor 548, the contacts 566 of the transfer key K565 at the first A operator position 500, C537, the contacts 632 and 633, the winding of R630, C527, the control conductor C526 of the trunk 520, the wiper 391 and engaged contact in the associated contact bank 392 of the sequence switch 380, C326, the upper winding of R350 and the contacts 358 to ground. Also, upon operating the hold relay R630 interrupts, at the contacts 634, the previously traced original series circuit for energizing the upper winding of the cutin relay R350 and the winding of the hold relay R630 including battery at the resistor 612. Further the hold relay R630 interrupts, at the contacts 636, the previously traced series circuit for energizing the winding of the control relay R610 and the winding of the release relay R620, thereby to cause the latter relays to restore. Also the hold relay R630 completes, at the contacts 635, the previously mentioned circuit for energizing the left-hand winding of the position relay R660, this circuit extending from ground by way of the contacts 635 and 651 and the left-hand winding of R660 to battery. When thus energized the position relay R660 operates to complete, at the contacts 661, a holding circuit for energizing the right-hand winding thereof in series with the winding of the control relay R670, this circuit extending from ground by way of the winding of R670, the contacts 667 and 661 and the right-hand winding of R660 to battery. Further the position relay R660 interrupts, at the contacts 662, the previously traced series holding circuit for energizing the winding of the control relay R670 and the right-hand winding of the position relay R650, thereby to cause the position relay R650 to restore. Also the position relay R660 prepares, at the contacts 663, a circuit for energizing the left-hand winding of the position relay R665 and completes, at the contacts 664, an obvious alternative path for applying ground potential to the control conductor C672. Upon restoring the position relay R650 prepares, at the contacts 654, a holding circuit for energizing in series the winding of the control relay R670 and the right-hand winding of the position relay R665, interrupts, at the contacts 653, a further point in the previously traced series holding circuit for energizing the winding of the control relay R670 in series with the right-hand winding of the position relay R650, and interrupts, at the contacts 651, the previously traced circuit for energizing the left-hand winding of the position relay R660.

Accordingly at this time the A operator position distributor 630 has operated in order to select the second A operator position to be used by the next calling telephone station, a circuit substantially identical to that previously traced being prepared for applying battery potential by way of the resistor 612 and the winding of the hold relay R640 to the control conductor C640 terminated by the ninth contact in the contact bank 392 associated with the wiper 391 of the sequence switch 380 and terminated by corresponding contacts in the corresponding contact banks of the other sequence switches. Also ground potential is applied by way of the upper winding of the cutin relay R350 and the wiper 361 to the control conductor C526 of the trunk 520 extending to the first A operator position 500. Hence the trunk 520 terminated by the other se-

quence switches is marked as busy thereto. In view of the above description of the mode of operation of the sequence switch 380 the call storage unit 600 and the A operator position distributor 630 in order to cause the sequence switch 380 to seize the trunk 520 extending to the first A operator position 500, it will be understood that the call storage unit 600 and the A operator position distributor 630 will cause the next operating sequence switch to seize the trunk line extending to the second A operator position.

Continuing now with the operation of the apparatus at the first A operator position 500 incident to the seizure of the trunk 520 extending to the first A operator position 500, it is noted that when the hold relay R630 operates it also completes, at the contacts 631, an obvious path for applying ground potential to the control conductor C528. The application of ground potential to the control conductor C528 completes a circuit for energizing the winding of the tone relay R515, this circuit extending from the grounded control conductor C528 by way of the contacts 528 and the winding of R515 to battery. When the winding of the tone relay R515 is thus energized this relay operates shortly thereafter, this relay being of the slow-to-operate type. Upon operating the tone relay R515 completes, at the contacts 516, an obvious circuit for energizing the winding of the tone relay R520, thereby to cause the latter relay to operate shortly thereafter, the latter relay being of the slow-to-operate type. Upon operating the tone relay R520 completes, at the contacts 523, an obvious circuit for energizing the winding of the tone relay R525, thereby to cause the latter relay to operate shortly thereafter, the latter relay being of the slow-to-operate type. Upon operating the tone relay R525 completes, at the contacts 527, an obvious holding circuit for energizing the winding thereof and interrupts, at the contacts 528, the previously traced circuit for energizing the winding of the tone relay R515, thereby to cause the latter relay to restore. Upon restoring the tone relay R515 interrupts, at the contacts 516, the previously mentioned circuit for energizing the winding of the tone relay R520, thereby to cause the latter relay to restore.

Assuming that the plugs associated with the transmitter 508 and the receiver 507 are inserted into the associated jacks J506 and J505 at this time, a circuit is completed for energizing in series the transmitter 508 and the control relay R510. This circuit extends from ground by way of the winding 502 of the repeater 501, the jack J505 and associated plug, the transmitter 508, the plug and associated jack J506 and the winding of R510 to battery. When the winding of the control relay R510 is thus energized it operates to interrupt, at the contacts 511, an obvious path for applying ground potential to the control conductor C526 of the trunk 520. At this point it is noted that when the plugs associated with the receiver 507 and the transmitter 508 are withdrawn from the associated jacks J505 and J506, the previously traced circuit for energizing the winding of the control relay R510 is interrupted, thereby to cause the latter relay to restore; whereupon the previously mentioned path for applying ground potential to the control conductor C526 of the trunk 520 is completed. When ground potential is applied to the control conductor C526 of the trunk 520 the trunk 520 is marked as busy to the sequence switches having access thereto. Hence it will be understood that

the first A operator position 500 is selectable by one of the sequence switches only when the plugs associated with the receiver 507 and the transmitter 508 are inserted into the associated jacks J505 and J506.

Also at this time the receiver 507 is operatively associated with the winding 504 of the repeater 501 by way of a circuit extending from one terminal of the receiver 507 over the plug and associated jack J506, the winding 504 and the jack 10 J505 and associated plug to the other terminal of the receiver 507.

Also upon operating the cutin relay R350 interrupts, at the contacts 353 and 356, the previously traced connection between the telephone line 225 and the trunk 360 and completes, at the contacts 352 and 355, a loop circuit between the calling subscriber substation T1 and the repeater 501 at the first operator position 500. This loop circuit extends from the line conductor C226 of the telephone line 225 by way of the wiper 311, the contacts 322, 332 and 352, the line conductor C322, the wiper 385 and engaged contact in the associated contact bank 388 of the sequence switch 380, the line conductor C522 of the trunk 520, the contacts 531 and 516, the windings 503 and 504 of the repeater 501, the condenser 509, the contacts 533, the line conductor C521 of the trunk 520, the wiper 383 and engaged contact in the associated contact bank 384 of the sequence switch 380, the line conductor C324, the contacts 355, 334 and 323 and the wiper 312 to the line conductor C227 of the telephone line 225, the line conductors C226 and C227 of the telephone line 225 being connected together by way of the bridge path at the calling subscriber substation T1. Also the cutin relay R350 completes, at the contacts 351 and 354, a loop circuit between the line relay R455 in the selector switch 400 and the repeater 501, this loop circuit extending from ground by way of the lower winding of R455, the lower winding of R450, the line conductor C362 of the trunk 360, the contacts 354, the line conductor C323, the wiper 387 and engaged contact in the associated contact bank 388 of the sequence switch 380, the line conductor C524 of the trunk 520, the contacts 544 and 538, the condenser 509, the windings 504 and 503 of the repeater 501, the contacts 516, the contacts 536 and 542, the line conductor C523 of the trunk 520, the wiper 389 and engaged contact in the associated contact bank 390 of the sequence switch 380, the line conductor C321, the contacts 351, the line conductor C361 of the trunk 360, the upper winding of R450 and the upper winding of R455 to battery. Also it is noted that the loop circuit extending between the repeater 501 and the calling subscriber substation T1, including the line conductors C521 and C522 of the trunk 520, and the loop circuit extending between the repeater 501 and the line relay R455 in the selector switch 400, including the line conductors C523 and C524 of the trunk 520, are metallically interconnected, and interconnected by the retarder coil 530, thereby to prevent restoration of the line relay R455 in the selector switch 400. Accordingly ground potential is supplied by way of the lower winding of the line relay R455 and the line conductor C524 of the trunk 520 to one terminal of the condenser 509; and battery potential is supplied by way of the upper winding of the line relay R455 and the line conductor C523 of the trunk 520 and the windings 503 and 504 of the repeater 501 to the other terminal of the condenser 509, the receiver

507 being arranged in a circuit including the winding 504 of the repeater 501, as previously noted.

Accordingly, when the tone relay R515 operates it interrupts, at the contacts 516, the previously traced connection between the windings 503 and 504 of the repeater 501 and the interconnected loop circuits respectively extending to the calling subscriber substation T1 and to the line relay R455 in the selector switch 400 and completes, at the contacts 517, an alternative circuit for charging the condenser 509 including the tone conductor C512. This circuit for charging the condenser 509 extends from the ungrounded terminal of a grounded source of tone current by way of the conductor C512, the contacts 522 and 517 and the windings 503 and 504 of the repeater 501 to one terminal of the condenser 509, the other terminal of the condenser 509 having ground potential connected thereto, as previously noted. Upon operating the tone relay R520 interrupts, at the contacts 522, the above-traced circuit for charging the condenser 509 and prepares, at the contacts 521, an alternative circuit for charging the condenser 509. Upon operating the tone relay R525 completes, at the contacts 526, the alternative circuit for charging the condenser 509, this circuit extending from the tone conductor C512 by way of the contacts 526, 521, 517 and the windings 503 and 504 of the repeater 501 to one terminal of the condenser 509, the other terminal of the condenser 509 having ground potential connected thereto, as previously noted. Finally when the tone relay R515 restores it interrupts, at the contacts 517, the above-traced alternative circuit for charging the condenser 509 and recomplete, at the contacts 516, the interconnection between the repeater 501 and the loop circuits respectively 40 extending to the calling subscriber substation T1 and to the line relay R455 in the selector switch 400. The alternate completion and interruption of the circuits for charging the condenser 509, including the tone conductor C512, causes the 45 winding 504 of the repeater 501 to be alternately energized and deenergized with tone current, thereby to cause the receiver 507 at the first A operator position 500 to be alternately operated, whereupon a distinct zip-zip tone is produced 50 thereby. The production of the zip-zip tone by the receiver 507 at the first A operator position 500 indicates to the operator thereat that an incoming call has been extended to her position by one of the sequence switches.

55 Finally, upon operating the hold relay R630 completes, at the contacts 631, a circuit for illuminating the flat rate signal lamp L680, in the present instance the signal relays R685 and R690 being restored at this time. The circuit for illuminating the flat rate signal lamp L680 extends from ground by way of the contacts 631 and 636 and L680 to battery. The illumination of the flat rate signal lamp L680 indicates to the operator at the first A operator position 500 that the incoming call which is extended to her position originates at a subscriber substation to which flat rate service is rendered and that it is not necessary to register the call.

At this time both the receiver 507 and the 70 transmitter 508 at the first A operator position 500 are operatively connected to the loop circuit extending to the calling subscriber substation T1. Accordingly the operator at the first A operator position 500 may converse with the subscriber at the calling subscriber substation T1 and as-

certain the destination of the call. After learning the destination of the call the operator at the first A operator position 500 initiates the extension of the call by operating the key sender K520 in order appropriately to control the selector switch 400.

Extension of a call from an A operator position

In order to extend a call from an A operator position, such, for example, as a call from the subscriber substation T1 to the first A operator position 500, the operator at the first A operator position 500 operates the key sender K520, thereby to cause the impulse relay R540 to operate. Upon operating the impulse relay R540 completes, at the contacts 541 and 543, an alternative loop circuit substantially identical to that previously traced between the line relay R455 in the selector switch 400 and the key sender K520 and interrupts, at the contacts 542 and 544, the previously traced loop circuit between the repeater 501 and the line relay R455 in the selector switch 400. The key sender K520 then operates to interrupt intermittently the previously mentioned alternative loop circuit extending to the selector switch 400, thereby to cause the line relay R455 to follow the impulses of the digit transmitted in the usual manner. Each time the line relay R455 restores it interrupts, at the contacts 456, the previously traced circuit for energizing the winding of the hold relay R460 and completes, at the contacts 457, the previously mentioned multiple circuit for energizing the lower winding of the transfer relay R465 and the vertical magnet M414. This circuit extends from ground by way of the contacts 475, 457, 464 and 467 and the lower winding of R465 to battery, and from the contacts 467 and the vertical magnet M414 to battery. Due to the fact that the hold relay R460 and the transfer relay R465 are of the slow-to-release type, these relays remain operated during impulsing. Each time the vertical magnet M414 is energized it operates, thereby to drive the wiper set of the mechanism 410 one step in the vertical direction. When the wiper set of the mechanism 410 is driven one step in the vertical direction the set of switch springs S420 is actuated into disengagement, thereby to interrupt the previously traced circuit for energizing the upper winding of the transfer relay R465; the set of switch springs S419 is actuated into engagement, thereby to prepare a circuit traced hereinafter for energizing the release magnet M418; and the set of switch springs S421 is actuated into engagement, thereby to prepare a circuit traced hereinafter for energizing the rotary magnet M416.

At the conclusion of the digit transmitted by the key sender K520 the impulse relay R540 restores, thereby to recomplete, at the contacts 542 and 544, the previously traced loop circuit extending between the repeater 501 and the line relay R455 in the selector switch 400 and to interrupt, at the contacts 541 and 543, the previously mentioned alternative loop circuit extending between the key sender K520 and the selector switch 400. Shortly following the conclusion of the digit transmitted from the key sender K520 to the selector switch 400 the transfer relay R465 restores to interrupt, at the contacts 467, a further point in the previously traced multiple circuit for energizing the lower winding thereof and the vertical magnet M414 and to complete, at the contacts 469', the previously mentioned circuit for energizing the rotary mag-

net M416. This circuit extends from ground by way of the contacts 476, 458, 417 and 469', the set of switch springs S421 and M416 to battery. When thus energized the rotary magnet M416 operates to drive the wiper set of the mechanism 410 one step in the rotary direction and to interrupt, at the contacts 417, the previously traced circuit for energizing the rotary magnet M416, thereby to cause the rotary magnet M416 to restore. Upon restoring the rotary magnet M416 recomplete, at the contacts 417, the previously traced circuit for energizing the rotary magnet M416. Accordingly the rotary magnet M416 operates intermittently, thereby to drive the wiper set of the mechanism 410 step by step in the rotary direction until the wiper 413 of the wiper set engages a contact terminating the control conductor of a trunk having battery potential thereon, battery potential being present upon the control conductor of the trunk in the event the trunk is idle, whereupon a circuit is completed for energizing the upper winding of the switching relay R470. The circuit for energizing the upper winding of the switching relay R470 extends from the grounded control conductor C363 of the trunk 360 by way of the contacts 427 and 454 and the upper winding of R470, the contacts 461 and the wiper 413 to the control conductor of the trunk having battery potential thereon.

When this circuit is completed the switching relay R470 operates exceedingly fast, thereby to complete, at the contacts 474, a holding circuit for energizing the intermediate winding thereof, this circuit extending from the grounded control conductor C363 of the trunk 360 by way of the contacts 427, 454 and 474 and the intermediate winding of R470 to battery. Also upon operating the switching relay R470 interrupts, at the contacts 475, the previously traced circuit for energizing the rotary magnet M416, thereby positively to arrest further operation of the wiper set of the mechanism 410. Further the switching relay R470 interrupts, at the contacts 475, the previously traced circuit for energizing the winding of the hold relay R460, thereby to cause the latter relay to restore shortly thereafter. Finally the switching relay R470 completes, at the contacts 471, 472 and 473, a connection between the selector switch 400 and the trunk seized by the wiper set of the mechanism 410, thereby to complete a loop circuit for energizing in series the upper and lower windings of the battery supply relay R430. This loop circuit extends from ground by way of the lower winding of R430, the contacts 472 and the wiper 412 to one of the line conductors of the seized trunk and from battery by way of the upper winding of R430, the contacts 471 and the wiper 411 to the other line conductor of the seized trunk, the line conductors of the seized trunk being connected together at the operator position terminating the seized trunk. When thus energized the battery supply relay R430 operates to complete, at the contacts 433, an obvious circuit for energizing the winding of the control relay R440, thereby to cause the latter relay to operate shortly thereafter, the latter relay being of the slow-to-operate type. Upon operating the control relay R440 completes, at the contacts 441, an obvious alternative path for applying ground potential to the control conductor C363 of the trunk 360. Further it is noted that the loop circuit extending between the repeater 501 and the line relay R455 in the selector switch 400 is operatively connected by the condensers 428 and

429 to the loop circuit extending between the battery supply relay R430 in the selector switch 400 and the trunk seized by the wiper set of the mechanism 410.

In the event the call which is extended from the first A operator position 500 is ultimately to be completed in the local exchange 20 the operator at the first A operator position 500 controls the key sender K520, thereby to cause the selector switch 400 to seize an idle trunk in the group of trunks extending to an idle one of the B operator positions in the local exchange 20. For example, the selector switch 400 may be controlled to seize an idle one of the trunks, such, for example, as the trunk 490 in the group of trunks extending to the idle first B operator position 494 in the local exchange 20. The trunk 490 extending to the first B operator position 494 is marked for seizure by the presence of battery potential upon the control conductor C493 thereof, the path for applying ground potential to the control conductor C493 of the trunk 490 extending from battery by way of the winding of the line relay R480 and the contacts 486 to the control conductor C493. When the switching relay R470 operates it completes, at the contacts 473, an obvious path for applying ground potential by way of the wiper 413 to the control conductor C493 of the trunk 490, thereby to complete an obvious circuit for energizing the winding of the line relay R480. When thus energized the line relay R480 operates to interrupt, at the contacts 481, a circuit for energizing the busy relay R485. Accordingly, at this time a loop circuit is completed between the battery supply relay R430 in the selector switch 400 and the first B operator position 494. When the trunk 490 is seized by the selector switch 400 a signal is transmitted to the first B operator position 494; whereupon the operator at the first B operator position 494 answers the call and communicates with the operator at the first A operator position 500 concerning the extension of the call to a called subscriber substation in the local exchange 20. The operator at the first B operator position 494 then proceeds to extend the call to the called subscriber substation in the local exchange 20 in the usual manner.

At this point it is noted that the operator at the first B operator position 494 may render the trunk 490 extending thereto busy by causing battery potential to be applied to the line conductor C492 of the trunk 490 prior to seizure of the trunk 490. The application of battery potential to the line conductor C492 of the trunk 490 completes an obvious circuit for energizing the winding of the busy relay R485, thereby to cause the latter relay to operate. Upon operating the busy relay R485 interrupts, at the contacts 486, the previously traced path for applying battery potential by way of the winding of the line relay R480 to the control conductor C493 of the trunk 490, and completes, at the contacts 487, an obvious path for applying ground potential to the control conductor C493 of the trunk 490, the application of ground potential to the control conductor C493 of the trunk 490 being effective to mark the trunk 490 as busy to the selector switches having access thereto.

Reconsidering now the operation of the selector switch 400 it is noted that in the event the call which is extended from the first A operator position 500 is ultimately to be completed in the distant exchange 30, the operator at the first A operator position 500 controls the key sender

K520, thereby to cause the selector switch 400 to seize an idle one of the trunk lines, such, for example, as the trunk line 470 in the group of trunk lines extending between the local exchange 20 and the B operator position 498 in the distant exchange 30, thereby to cause the trunk line circuit 472 individually associated with the trunk line 470 to operate in a manner similar to the trunk line circuit 480 previously described. When the trunk line 470 is seized by the selector switch 400 a signal is transmitted to the B operator position 498 in the distant exchange 30; whereupon the operator at the B operator position 498 answers the call and is advised by the operator at the first A operator position 500 concerning the extension of the call to a subscriber substation in the distant exchange 30. The operator at the B operator position 498 then extends the call to the called subscriber substation in the distant exchange 30 in the usual manner.

Considering further the operation of the selector switch 400 it is noted that in the event the call which is extended from the first A operator position 500 is a toll call, the operator at the first A operator position 500 controls the key sender K520, thereby to cause the selector switch 400 to seize an idle one of the trunks in one of the groups of trunks extending to an idle one of the toll operator positions, such, for example, as the trunk 495 in the group of trunks extending to the toll operator position 499, thereby to cause the trunk line circuit 497 individually associated with the trunk 495 to operate in a manner similar to the trunk line circuit 480 previously described. When the trunk 495 is seized by the selector switch 400 a signal is transmitted to the toll operator position 499; whereupon the operator at the toll operator position 499 answers the call and is advised by the operator at the first A operator position 500 concerning the routing of the call. The operator at the toll operator position 499 then routes the call toll in the usual manner.

Again considering the operation of the selector switch 400 to extend the call from the first A operator position 500 to the first B operator position 494, it is noted that when the battery supply relay R430 operates it prepares, at the contacts 431, a circuit for energizing the busy relay R220 in the flat rate line circuit 200 individually associated with the telephone line 225. Further it is noted that the circuit for energizing the winding of the busy relay R220 is completed in the event the link illustrated is the last available link, rendering all of the links busy at this time. In this event the circuit for energizing the winding of the busy relay R220 is completed and extends from ground by way of the chain conductor C443, the contacts 431, C231 and the winding of R220 to battery. When thus energized the busy relay R220 operates to interrupt, at the contacts 221, a point in the previously traced path for applying ground potential to the start conductor C230. Further it is noted that a path is normally completed for short-circuiting the winding 218 of the transformer 216 which extends from ground by way of the contacts 221 and the winding 218 of the transformer 216 to ground. Accordingly, upon operating the busy relay R220 interrupts, at the contacts 221, the above-traced path for short-circuiting the winding 218 of the transformer 216. Similarly the busy relay in each of the flat rate line circuits in the group of flat rate line circuits including the line circuit 200 is operated. Accord-

ingly, when the next call is initiated at one of the subscriber substations in the group of subscriber substations, including the subscriber substation T₁, the operation of the line and cut-off relay in the flat rate line circuit individually associated therewith will not cause ground potential to be applied to the start conductor C230 but will cause busy tone current to be returned to the receiver of the telephone instrument at the calling subscriber substation. By way of example, the analogous circuit for returning busy tone current over the telephone line 225 to the receiver of the telephone instrument at the subscriber substation T₁ under these operating conditions extends from ground by way of the winding 218 of the transformer 216, the contacts 215 and 214, the condenser 219, the contacts 211, C228, the bridge path between the line conductors C226 and C227 of the telephone line 225 at the subscriber substation T₁, C227, the contacts 212 and the lower winding of R210 to ground; the winding 217 of the transformer 216 being connected to a suitable source of busy tone current and being inductively coupled to the winding 218.

In connection with the extension of the call from the first B operator position 494 to a called telephone station in the local exchange 20 after the call has been answered at the first B operator position 494, it is noted by way of example, that the call may be extended to either one of the subscriber substations T₁ or T₂ by inserting the calling plug of the cord circuit at the first B operator position 494 into the jack J220 terminating the telephone line 270 extending to the subscriber substations T₂ and T₃.

When the operator at the first A operator position 500 extends the call from her position to the first B operator position 494 she may wish to converse with the operator at the first B operator position 494 to the exclusion of the subscriber at the calling subscriber substation T₁. In order to accomplish this result the operator at the first A operator position 500 operates the split key K575, thereby to complete, at the contacts 579 thereof, an obvious circuit for energizing the rear split relay R530 and to complete, at the contacts 576 and 577 thereof, an obvious connection between the impedance element I558 and the control conductors C546 and C547. Also when the split key K575 is operated an obvious connection is completed at the contacts 578 thereof between the line conductors C521 and C522 of the trunk 520 including the condenser 546. When thus energized the rear split relay R530 operates to interrupt, at the contacts 531 and 533, the previously traced loop circuit extending between the calling subscriber substation T₁ and the repeater 501 and to complete, at the contacts 532 and 534, an alternative loop circuit between the calling subscriber substation T₁ and the impedance element I558. This alternative loop circuit extends from ground by way of the lower winding of the impedance element I558, the contacts 576 of the split key K575, C547 and the contacts 534 to the line conductor C521 of the trunk 520, and from battery by way of the upper winding of the impedance element I558, the contacts 577 of the split key K575, C546, and the contacts 532 to the line conductor C522 of the trunk 520; the line conductors C521 and C522 of the trunk 520 being included in the previously traced loop circuit extending to the calling subscriber substation T₁. With the split key K575 thus operated, the operator at the first A operator position

500 may converse with the operator at the first B operator position 494 to the exclusion of the subscriber at the calling subscriber substation T₁. After the termination of the conversation between the operators at the first A operator position 500 and the first B operator position 494 the operator at the first A operator position 500 returns the split key K575 to its normal position, thereby to interrupt, at the contacts 578, the previously mentioned circuit for energizing the winding of the rear split relay R530; whereupon the rear split relay R530 restores to recomplete, at the contacts 531 and 533, the previously traced loop circuit between the calling subscriber substation T₁ and the repeater 501. Also, at the contacts 576 and 577 of the split key K575, the impedance element I558 is disconnected from the control conductors C546 and C547.

In the event the operator at the first A operator position 500 should make an error in registering the digit to be transmitted to the selector switch 400 upon the key sender K520, the operated selector switch 400 may be restored to its normal position by operating the error release key K550 at the first A operator position 500. When the error release key K550 is thus operated an obvious circuit is completed, at the contacts 582 thereof, for energizing the winding of the front split relay R538, thereby to cause the latter relay to operate and complete, at the contacts 539, a path for applying ground potential to the line conductor C382 of the trunk 360, this path extending from ground by way of the contacts 551 of the error release key K550, the contacts 539 and 544, the line conductor C524 of the trunk 520, the wiper 387 and engaged contact in the associated contact bank 388 of the sequence switch 388, the line conductor C323 and the contacts 354 to the line conductor C382 of the trunk 360. This application of ground potential to the line conductor C382 of the trunk 360 completes an obvious path for short-circuiting in series the lower winding of the error relay R450 and the lower winding of the line relay R455. When the lower winding of the line relay R455 is thus short-circuited this relay remains in its operated position; however, when the lower winding of the error relay R450 is thus short circuited this relay operates, as the error relay R450 is of the differential type. Upon operating the error relay R450 completes, at the contacts 451, a circuit for energizing the winding of the lockout relay R425, this circuit extending from ground by way of the contacts 551 of the error release key K550, the resistor 505, the contacts 537 and 542, the line conductor C523 of the trunk 520, the wiper 389 and engaged contact in the associated contact bank 388 of the sequence switch 388, the line conductor C321, the contacts 351, the line conductor C361 of the trunk 360, the contacts 451 and the winding of R425 to battery. When this circuit for energizing the winding of the lockout relay R425 is completed, the latter relay does not operate due to the series resistance of this circuit, the lockout relay R425 being of the marginal type. Also the error relay R450 completes, at the contacts 453, an obvious alternative path for applying ground potential to the control conductor C363 of the trunk 360, thereby to retain the finder switch 300 in its operated position and to interrupt, at the contacts 454, the previously traced holding circuit for energizing the intermediate winding of the switching relay R470, thereby to cause the latter relay to restore. Finally the error relay R450 completes, at the contacts 455 and 456, the winding of the lockout relay R425 to battery.

tacts 452, a circuit for energizing the release magnet M418, this circuit extending from ground by way of the contacts 452, the release magnet M418 and the set of switch springs S419 to battery. When thus energized the release magnet M418 operates to release the wiper set of the mechanism 410 and to cause this wiper set to be returned to its normal position.

Accordingly, in order to release the operated selector switch 400 it is only necessary for the operator at the first A operator position 500 to operate the error release key K550 momentarily and then return it to its normal position. When the error release key K550 is returned to its normal position the previously mentioned circuit for energizing the winding of the front split relay R535 is interrupted, at the contacts 552 thereof, and the previously traced path for short-circuiting in series the lower winding of the error relay R450 and the lower winding of the line relay R455 is interrupted, at the contacts 551 thereof. Accordingly, the front split relay R535 then restores to recomplete, at the contacts 536 and 538, the previously traced loop circuit between the repeater 501 and the line relay R455 in the selector switch 400. Also the error relay R450 restores in order to interrupt, at the contacts 452, a further point in the previously traced circuit for energizing the release magnet M418. At this time the selector switch 400 is completely released and is in condition to be responsive to impulses transmitted thereto from the key sender K520. Accordingly the operator at the first A operator position 500 again operates the key sender K520 in accordance with the proper digit, thereby to control the selector switch 400 in the manner previously explained.

After the call has been extended from the first A operator position 500 to the first B operator position 494 the operator at the first A operator position 500 causes the call to be transferred directly from the calling subscriber substation T1 to the first B operator position 494 by operating the transfer key K565. When the transfer key K565 is thus operated an obvious circuit is completed at the contacts 567 for energizing the magnet M547 of the peg count meter associated with the first A operator position 500, whereupon the peg count meter operates to register the extension of a call by the operator at the first A operator position 500. Also when the transfer key K565 is thus operated the previously traced holding circuit for energizing in series the winding of the hold relay R630 and the upper winding of the cutin relay R350 is interrupted at the contacts 566 thereof, thereby to cause the hold relay R630 and the cutin relay R350 to restore. The transfer key K565 is then returned to its normal position.

Upon restoring the hold relay R630 interrupts, at the contacts 631, the previously traced circuit for illuminating the flat rate signal lamp L680 and the previously traced holding circuit for energizing the winding of the tone relay R525, thereby to cause the signal lamp L680 to be extinguished and to cause the tone relay R525 to restore. At this time the first A operator position 500 is idle and is available to be assigned for use by the A operator position distributor 630.

Upon restoring the cutin relay R350 interrupts, at the contacts 352 and 355, the previously traced loop circuit between the calling subscriber substation T1 and the repeater 501, interrupts, at the contacts 351 and 354, the previously traced loop circuit between the line relay R455 in the

selector switch 400 and the repeater 501, and completes, at the contacts 353 and 356, a direct loop circuit between the calling subscriber substation T1 and the line relay R455 in the selector switch 400. The direct loop circuit between the calling subscriber substation T1 and the line relay R455 in the selector switch 400 extends from ground by way of the lower winding of R455, the lower winding of R450, the line conductor C362 of the trunk 360, the contacts 356, 334 and 323 and the wiper 312 to the line conductor C227 of the telephone line 225, and from battery by way of the upper winding of R455, the upper winding of R450, the line conductor C361 of the trunk 360, the contacts 353, 332 and 322 and the wiper 311 to the line conductor C226 of the telephone line 228, the line conductors C226 and C227 of the telephone line 225 being connected together by way of the bridge path at the calling subscriber substation T1. Moreover, the direct loop circuit extending between the calling subscriber substation T1 and the line relay R455 in the selector switch 400 is interconnected by the condensers 428 and 429 with the loop circuit extending between the battery supply relay R430 in the selector switch 400 and the first B operator position 494. Accordingly, at this time the subscriber at the calling subscriber substation T1 may converse with the operator at the first B operator position 494; and may ultimately converse with the called subscriber substation after the operator at the first B operator position 494 has extended the connection to the called subscriber substation in the local exchange 20.

35 *Recall of an A operator position from a B operator position*

After the connection from the calling subscriber substation T1 has been transferred from the first A operator position 500 directly by way of the link illustrated to the first B operator position 494, the operator at the first B operator position 494 may have occasion to recall an A operator position. An idle A operator position may be recalled over the established connection between the calling subscriber substation T1 and the first B operator position 494, including the link illustrated, under the control of the operator at the first B operator position 494. In order to accomplish this end the operator at the first B operator position 494 operates the apparatus at her position, thereby to cause the loop circuit extending between the battery supply relay R430 in the selector switch 400 and the first B operator position 494 to be momentarily interrupted and then recompleted, thereby to cause the battery supply relay R430 instantaneously to restore and reoperate. Upon restoring the battery supply relay R430 interrupts, at the contacts 433, the previously mentioned circuit for energizing the winding of the control relay R440 and completes, at the contacts 434, an obvious circuit for energizing the lower winding of the call-back relay R445. The control relay R440, being of the slow-to-operate type, is also slightly slow to release. Accordingly the control relay R440 does not immediately restore and when the battery supply relay R430 reoperates it recompiles, at the contacts 433, the previously mentioned circuit for energizing the winding of the control relay R440. When the previously mentioned circuit for energizing the lower winding of the call-back relay R445 is completed the latter relay operates to complete, at the contacts 446, a holding circuit for energizing the upper

winding thereof in series with the intermediate winding of the cutin relay R350 in the finder switch 300, the battery supply relay R430 being reoperated at this time. The holding circuit for energizing the upper winding of the call-back relay R445 in series with the intermediate winding of the cutin relay R350 extends from ground by way of the upper winding of R445, the contacts 446 and 432, the control conductor C364 of the trunk 360 and the intermediate winding of the cutin relay R350 to battery. As previously noted, the cutin relay R350 does not operate when the intermediate winding thereof is energized; however, while the intermediate winding of the cutin relay R350 is energized this relay becomes exceedingly fast to operate when the upper winding thereof is subsequently energized.

Also upon operating, the call-back relay R445 completes, at the contacts 446, a circuit for energizing the upper winding thereof in series with the rotary magnet M393 of the sequence switch 380, this circuit extending from ground by way of the upper winding of R445, the contacts 446 and 432, the control conductor C364 of the trunk 360, the contacts 350 and 394 and the rotary magnet M393 to battery. When the rotary magnet M393 is thus energized it operates intermittently in order to cause the wipers noted of the sequence switch 380 to be driven step by step in the clockwise direction, in the manner previously explained. More particularly, the wiper 391 engages the seventh contact in the associated contact bank 392 of the sequence switch 380, thereby to cause the marking relay 1M in the call storage unit 600 to operate and cause operation of the release relay R620 and the control relay R610, in the manner previously explained, assuming that there is an idle A operator position at this time. The operation of the release relay R620 causes the hold relay in the A operator position distributor 630 corresponding to the A operator position previously selected by the A operator position distributor 630 to be conditioned for operation, thereby to assign the previously selected A operator position for use, in the manner previously explained. Also the operation of the release relay R620 causes further operation of the sequence switch 380, whereupon the A operator position assigned for use is selected by the sequence switch 380 in the manner previously explained. When the A operator position assigned for use is selected by the sequence switch 380 a series circuit substantially identical to that previously traced is completed for energizing the upper winding of the call-back relay R445, the upper winding of the cutin relay R350 and the winding of the corresponding hold relay in the A operator position distributor 630, this circuit extending from ground at one terminal of the upper winding of the call-back relay R445 to battery at the resistor 612. Accordingly the cutin relay R350 operates at this time to interrupt, at the contacts 350, the previously traced circuit for energizing the winding of the rotary magnet M393, thereby positively to arrest further operation of the sequence switch 380. Further the cutin relay R350 completes, at the contacts 358 and 359, the previously traced holding circuit for energizing the lower winding thereof and completes, at the contacts 358, an obvious path for short-circuiting the upper winding of the call-back relay R445. When the above-traced circuit for energizing the lower winding of the cutin relay R350 is completed the cutin relay R350 is rendered exceedingly fast to restore when the

series circuit for energizing the upper winding thereof is interrupted by operation of the transfer key at the selected A operator position, in the manner previously explained. When the upper winding of the call-back relay R445 is thus short-circuited this relay is rendered additionally slow to release, this relay being ordinarily of the slow-to-release type. After a considerable time interval the call-back relay R445 restores to interrupt, at the contact 446, the previously traced path for applying ground potential to the control conductor C364 of the trunk 360. However, prior to the restoration of the call-back relay R445 the recall on the link illustrated is routed to an idle one of the A operator positions to be answered even though the recall thereon is first stored in the call storage unit 600 in a manner more fully explained hereinafter. Finally upon operating, the cutin relay R350 completes, at the contacts 352 and 355, a loop circuit substantially identical to that previously traced between the calling subscriber substation T1 and the repeater at the selected A operator position; and completes, at the contacts 351 and 354, a loop circuit substantially identical to that previously traced between the line relay R455 in the selector switch 400 and the repeater at the selected A operator position. Accordingly at this time, the operator at the selected A operator position may converse with either the subscriber at the subscriber substation T1 or the operator at the first B operator position 494. Hence it will be understood that in the event a subscriber at the calling subscriber substation T1 desires another connection the operator at the selected A operator position may release the selector switch 400 by operating the error release key at her position; and subsequently reoperate the selector switch 400 by operating the key sender at her position, thereby to establish another connection between the calling subscriber substation T1 and any desired called operator position.

Release of an established connection between a calling subscriber substation and a called operator position

The release of an established connection between a calling subscriber substation, such, for example, as the calling subscriber substation T1 and a called operator position, such, for example, as the first B operator position 494 routed therebetween by way of the link illustrated, is primarily under the control of the operator at the first B operator position 494. It is noted that the operator at the first B operator position 494 releases the connection from her position to the called subscriber substation in the local exchange 20 by operating the apparatus at her position, in the usual manner, and initiates the release of the established connection between her position and the selector switch 400 by interrupting the loop circuit between the battery supply relay R430 in the selector switch 400 and the first B operator position 494, thereby to cause the battery supply relay R430 to restore. Upon restoring the battery supply relay R430 interrupts, at the contacts 433, the previously mentioned circuit for energizing the winding of the control relay R440, thereby to cause the latter relay to restore. Upon restoring the control relay R440 interrupts, at the contacts 441, the previously traced path for applying ground potential to the control conductor C363 of the trunk 360, thereby to interrupt the previously traced holding circuit for energizing the intermediate winding of the switching relay R470. The

switching relay R470 then restores to prepare, at the contacts 475, the previously mentioned circuit for energizing the release magnet M418.

Also when ground potential is removed from the control conductor C383 of the trunk 360 the previously traced holding circuit for energizing the intermediate winding of the switching relay R320 in the finder switch 300 is interrupted, thereby to cause the latter relay to restore. Upon restoring, the switching relay R320 completes, at the contacts 321, the previously mentioned circuit for energizing the release magnet M369, this circuit extending from ground by way of the contacts 321, 331 and 341, the set of switch springs S370 and M369 to battery. When thus energized the release magnet M369 operates to release the first and second wiper sets of the mechanism 310 and to cause these wiper sets to be returned to their normal positions, whereupon the sets of switch springs S370, S371 and S372 are actuated. More particularly, the set of switch springs S370 is actuated into disengagement, thereby to interrupt the previously traced circuit for energizing the release magnet M369 in order to cause the release magnet M369 to restore. The set of switch springs S372 is actuated into engagement, thereby to complete the previously traced path for applying ground potential to the all-link-busy conductor C309. Finally the contacts 372 of the set of switch springs S371 are actuated into disengagement, thereby to interrupt the previously traced path for applying ground potential to the guard conductor C303. At this time the finder switch 300 is completely released.

When the finder switch 300 is released the previously traced loop circuit between the calling subscriber substation T1 and the line relay R455 in the selector switch 400 is interrupted, thereby to cause the latter relay to restore. Upon restoring the line relay R455 completes, at the contacts 451, the previously mentioned circuit for energizing the release magnet M418, this circuit extending from ground by way of the contacts 475, 451, 460 and 469, M418 and the set of switch springs S419 to battery. When thus energized the release magnet M418 operates to release the wiper set of the mechanism 410 and to cause this wiper set to be returned to its normal position, whereupon the sets of switch springs S419, S420 and S421 are actuated. More particularly the set of switch springs S419 is actuated into disengagement, thereby to interrupt the previously traced circuit for energizing the release magnet M418, thereby to cause the release magnet M418 to restore. The set of switch springs S421 is actuated into disengagement, thereby to interrupt a further point in the previously traced circuit for energizing the rotary magnet M416; and the set of switch springs S420 is actuated into engagement, thereby to prepare the previously traced circuit for energizing the upper winding of the transfer relay R465. At this time the selector switch 400 is completely released.

When the selector switch 400 is released the previously traced circuit for energizing the winding of the line relay R480 in the trunk line circuit 480 individually associated with the trunk 490 extending to the first B operator position 494 is interrupted, thereby to cause the line relay R480 to restore. Upon restoring the line relay R480 prepares, at the contacts 481, the previously traced circuit for energizing the winding of the busy relay R485. At this time the trunk line

5 circuit 480 is completely released and battery potential is applied by way of the winding of the line relay R480 to the control conductor C493 of the trunk 490, thereby to mark the trunk 490 as idle. Accordingly at this time, the apparatus at the first B operator position 494 utilized in the established connection between the calling subscriber substation T1 and the first B operator position 494 is completely released.

10 Assuming that the subscriber at the calling subscriber substation T1 has replaced the receiver of the telephone instrument thereat upon its switchhook, when the finder switch 300 is released the previously traced circuit for energizing the intermediate winding of the line and cutoff relay R210 in the flat rate line circuit 200 individually associated with the telephone line 225 extending to the subscriber substation T1 is interrupted, thereby to cause the line and cutoff relay R210 to restore. At this time battery potential is applied by way of the intermediate winding of the line and cutoff relay R210 to the control conductor C229 of the telephone line 225, thereby to mark the telephone line 225 15 extending to the subscriber substation T1 as idle. At this time the flat rate line circuit 200 individually associated with the telephone line 225 extending to the subscriber substation T1 is completely released.

30 *Party subscriber substation call*

A call from a party subscriber substation, such, for example, as the party subscriber substation T2, is initiated by removing the receiver of the 35 telephone instrument thereat from its switchhook. When the receiver of the telephone instrument at the subscriber substation T2 is removed from its switchhook, a bridge path is completed between the line conductors C271 and C272 of the telephone line 270 extending to the subscriber substation T2. When this bridge path is completed between the line conductors of the telephone line 270 a circuit is completed for energizing in series the windings of the line and cutoff relay R260. This circuit extends from ground by way of the lower winding of R260, the contacts 262, 254 and 249 to C272, the bridge path between the line conductors C272 and C271, C271, the contacts 246, 251 and 261 and the upper and intermediate windings of R260 to battery. When thus energized over the above-traced circuit the line and cutoff relay R260 operates partially, thereby to complete, at the contacts 264, an obvious path for applying ground potential to the start conductor C266 and to complete, at the contacts 263, an obvious connection between the control conductors C275 and C273 of the telephone line 270. The application of ground potential to the start conductor C266 completes an obvious path for applying ground potential by way of the resistor 303 of the marking network 305 to the start conductor C308 extending to the distributor 301 and an obvious path for applying direct ground potential to the 45 second contacts in the vertical control contact banks of the finder switches. The application of ground potential to the start conductor C308 initiates operation of the distributor 301 and the application of direct ground potential to the second contacts in the vertical control contact banks of the finder switches marks the telephone line 270 as terminating in the second level of the main contact banks of the finder switches.

The finder distributor 301 then operates to 50 cause the previously selected link to be assigned

to the use of the calling subscriber substation T2 in the previously described manner. Assuming that the distributor 301 operates to assign the link illustrated to the use of the calling subscriber substation T1, the finder switch 300 operates, in the previously described manner, to seize the telephone line 270 extending to the calling subscriber substation T2. Also the selector switch 400 and the sequence switch 380 operate in the manners previously described. Assuming that the A operator position distributor 630 has previously selected the first A operator position 500 for use at this time, the sequence switch 380 operates to seize the trunk 520 extending to the first A operator position 500, in the manner previously explained.

At this point it is noted that the operation of the finder switch 300 to seize the telephone line 270 is only slightly different from the operation thereof to seize the telephone line 225, previously explained; the difference in the operation of the finder switch 300 residing in the fact that the telephone line 225 is terminated by the first section of the main contact bank associated with the first wiper set of the mechanism 310, while the telephone line 270 is terminated by the second section of the main contact bank associated with the second wiper set of the mechanism 310. Accordingly, during the operation of the finder switch 300 at this time, when the second wiper set engages the contact set in the second section of the main contact bank of the mechanism 310 terminating the telephone line 270 a circuit is completed for energizing the upper winding of the switching relay R330, this circuit extending from ground by way of the contacts 342, the upper winding of R330, the contacts 326, the wiper 316, the control conductor C275 of the telephone line 270, the contacts 263 and the intermediate winding of R260 to battery. When thus energized the switching relay R330 operates to complete, at the contacts 338, a holding circuit for energizing the intermediate winding thereof, this circuit extending from ground by way of the contacts 342 and 338 and the intermediate winding of R330 to battery. Further the switching relay R330 interrupts, at the contacts 336, a further point in the previously traced holding circuit for energizing the intermediate winding of the switching relay R320, thereby positively to prevent the latter relay from being retained in its operated position at this time in the event it is operated. Further the switching relay R330 interrupts, at the contacts 330, the previously traced circuit for energizing the rotary magnet M367, thereby positively to arrest further operation of the rotary magnet M367 at this time. Also the switching relay R330 completes, at the contacts 337, a low resistance circuit for energizing the intermediate winding of the line and cutoff relay R260, this circuit extending from ground by way of the contacts 342 and 337, the wiper 316, the control conductor C275 of the telephone line 270, the contacts 263 and the intermediate winding of R260 to battery. When thus energized the line and cutoff relay R260 operates completely, thereby to interrupt, at the contacts 265, the previously mentioned path for applying ground potential to the start conductor C266 in order to arrest further operation of the distributor 301. Also the line and cutoff relay R260 interrupts, at the contacts 261 and 262, the previously traced circuit for energizing the windings thereof across the line conductors C271 and C272 of the telephone line 270, thereby to

clear the telephone line 270 of impedance elements.

Finally the switching relay R330 completes, at the contacts 333 and 335, a loop circuit between the calling subscriber substation T2 and the repeater 501 at the first A operator position, assuming that the sequence switch 380 has operated to seize the trunk 520 extending to the first A operator position 500 at this time. This loop circuit extends from the line conductor C271 of the telephone line 270 by way of the contacts 246 and 251, C271, the wiper 314, the contacts 333 and 352, the line conductor C322, the wiper 385 and engaged contact in the associated contact bank 386 of the sequence switch 380, the line conductor C522 of the trunk 520, the contacts 531 and 516, the windings 503 and 504 of the repeater 501, the condenser 509, the contacts 533, the line conductor C521 of the trunk 520, the wiper 383 and engaged contact in the associated contact bank 384 of the sequence switch 380, the line conductor C324, the contacts 385 and 335, the wiper 315, C274 and the contacts 254 and 249 to the line conductor C272 of the telephone line 270, the receiver of the telephone instrument at the calling subscriber substation T2 being connected across the line conductors C271 and C272 of the telephone line 270. Also at this time the previously traced loop circuit between the line relay R455 in the selector switch 400 and the repeater 501 at the first A operator position 500 is completed.

Further it is noted that when the cutin relay R350 in the finder switch 300 operates it completes, at the contacts 351, a circuit for energizing in series the control relay R245 in the two-party line register circuit 240 individually associated with the telephone line 270 extending to the calling subscriber substation T2 and the windings of the signal relays R685 and R690. This circuit extends from ground by way of the resistor 244, R245, the control conductor C278 of the telephone line 270, the wiper 317, the contacts 351, the control conductor C325, the wiper 381 and engaged contact in the associated contact bank 382 of the sequence switch 380, the control conductor C525 of the trunk 520, the contacts 582 of the control key K560, the contacts 592 of the second register key K590, the contacts 597 of the first register key K595, C529, R685 and R690 to battery. When this series circuit is completed the signal relay R685 operates; however, the control relay R245 and the signal relay R690 do not operate due to the high series resistance of this circuit. Upon operating the signal relay R685 completes, at the contacts 687, a circuit for illuminating the message register signal lamp L681, this circuit extending from ground by way of the contacts 631, 687 and 691 and the signal lamp L681 to battery. The illumination of the message register signal lamp L681 indicates to the operator at the first A operator position 500 that the calling subscriber substation is rendered message register service. Accordingly, when the operator at the first A operator position answers the call she requests the subscriber at the calling subscriber substation to identify his subscriber substation. In the present instance, the calling subscriber substation T2 corresponds to the second message register in the two-party line register circuit 240. Accordingly the operator at the first A operator position subsequently operates the second register key K590 in order to operate the second register in the two-party line register circuit 240. When the second register

key K590 is operated an obvious circuit is completed at the contacts 594 thereof for energizing the rear split relay R530, thereby to cause the latter relay to operate and complete, at the contacts 532 and 534, a connection between the line conductors C522 and C521 of the trunk 520 and the control conductors C546 and C547. Also when the second register key K590 is operated the previously traced series circuit for energizing the winding of the control relay R245 and the windings of the signal relays R685 and R690 is interrupted at the contacts 592 thereof. Also, at the contacts 591 of the second register key K590, a circuit is completed for energizing the winding of the control relay R245, this circuit extending from ground by way of the resistor 244, R245, the control conductor C276 of the telephone line 270, the wiper 317, the contacts 351, the control conductor C325, the wiper 381 and engaged contact in the associated contact bank 382 of the sequence switch 380, the control conductor C525 of the trunk 520, the contacts 562 of the control key K560, C538, the contacts 591 of the second register key K590 and the resistor 564 to battery. When thus energized the control relay R245 operates, thereby to complete, at the contacts 247 and 248, obvious connections between the second and first register magnets M241 and M242, respectively, and the line conductors C277 and C274, respectively, of the telephone line 270. Finally when the second register key K590 is operated there is completed, at the contacts 593, a circuit for energizing the second register magnet M241, this circuit extending from ground by way of the second register magnet M241, the contacts 247 and 251, the line conductor C277 of the telephone line 270, the wiper 314, the contacts 333 and 352, the line conductor C322, the wiper 385 and engaged contact in the associated contact bank 386 of the sequence switch 380, the line conductor C522 of the trunk 520, the contacts 532, C546, the contacts 593, C549 and the resistor 563 to battery. When thus energized the second register magnet M241 operates in order to cause the second register to register a call at the calling subscriber substation T2.

After the second register key K590 is thus operated it is returned to its normal position, whereupon the previously traced circuit for energizing the winding of the rear split relay R530 is interrupted at the contacts 594 thereof and the previously traced circuit for energizing the winding of the control relay R245 is interrupted at the contacts 591 thereof, thereby to cause the control relay R245 and the rear split relay R530 to restore. Also, at the contacts 593 of the second register key K590, a further point in the previously traced circuit for energizing the second register magnet M241 is interrupted and, at the contacts 592, the previously traced series circuit for energizing the winding of the control relay R245 and the windings of the signal relays R685 and R690 is recompleted.

The extension of the call from the first A operator position 500 to one of the called operator positions, such, for example, as the first B operator position 494, and the subsequent completion of a direct connection between the calling subscriber substation T2 and the first B operator position 494 are the same as those previously explained. Also the release of the established connection between the calling subscriber substation T2 and the first B operator position 494 is the same as that previously explained.

From the foregoing explanation of the extension of a call from the calling subscriber substation T2 to an idle A operator position, such, for example, as the first A operator position 500, it will be understood that a call from the subscriber substation T3 is extended to the first A operator position 500 in precisely the same manner as the extension of the call from the calling subscriber substation T2 to the first A operator position 500. However, it is noted that after the operator at the first A operator position 500 answers the call and communicates with the subscriber at the calling subscriber substation T3 the first register key K595, instead of the second register key K590, is operated, thereby to cause the first register in the two-party line circuit 240 corresponding to the calling subscriber substation T3 to be operated.

More particularly, at this time when the first register key K595 is operated there is completed, at the contacts 599 thereof, an obvious circuit for energizing the winding of the rear split relay R530, thereby to cause the latter relay to operate. Also, at the contacts 596 of the first register key K595, there is completed a circuit substantially identical to that previously traced for energizing the winding of the control relay R245, thereby to cause the latter relay to operate. Further, at the contacts 597 of the first register key K595, the previously traced series circuit for energizing the winding of the control relay R245 and the windings of the signal relays R685 and R690 is interrupted. Finally, at the contacts 598 of the first register key K595, a circuit is completed for energizing the first register magnet M242, this circuit extending from ground by way of the first register magnet M242, the contacts 248 and 254, the line conductor C274 of the telephone line 270, the wiper 315, the contacts 335 and 355, the line conductor C324, the wiper 383 and engaged contact in the associated contact bank 384 of the sequence switch 380, the line conductor C521 of the trunk 520, the contacts 534, C547, the contacts 598 of the first register key K595, C549 and the resistor 563 to battery. When thus energized the first register magnet M242 operates to cause the first register corresponding to the subscriber substation T3 to operate, thereby to register the call at the subscriber substation T3.

When the first register key K595 is restored to its normal position the previously traced circuits for energizing the winding of the control relay R245 and the first register magnet M242 are respectively interrupted, at the contacts 596 and 598 thereof. Also, at the contacts 599 of the first register key K595, the previously mentioned circuit for energizing the winding of the rear split relay R530 is interrupted. Finally, at the contacts 597 of the first register key K595, the previously traced series circuit for energizing the winding of the control relay R245 and the windings of the signal relays R685 and R690 is recompleted. Accordingly, at this time the first register magnet M242, the control relay R245 and the rear split relay R530 restore, while the signal relay R685 reoperates.

What has been said with reference to the extension of the call from the first A operator position 500 to one of the called operator positions and the subsequent release of the established connection between the calling subscriber substation and the called operator position applies directly to the call initiated at the calling subscriber substation T3.

Reverting call between party subscriber substations

A reverting call which is to be extended from one party subscriber substation, such, for example, as the party subscriber substation T₂, to another party subscriber substation T₃ on the same telephone line 270 is first initiated at the calling subscriber substation T₂ and extended to one of the A operator positions, in the manner previously explained. Assuming that the call is extended from the calling subscriber substation T₂ by way of the link illustrated to the first A operator position 500, the operator at the first A operator position 500 first answers the call and is advised by the subscriber at the subscriber substation T₂ that the call is to be extended to the called subscriber substation T₃ on the same telephone line 270. The operator at the first A operator position 500 then advises the subscriber at the calling subscriber substation T₂ to replace the receiver of the telephone instrument thereat upon its switchhook and then operates the reverting call key K570, thereby to complete, at the contacts 573 thereof, an obvious circuit for energizing the winding of the rear split relay R530 and to complete, at the contacts 571 and 572 thereof, a circuit for projecting ringing current over the telephone line 270 upon operation of the rear split relay R530. This circuit extends from one terminal of a source of ringing current, not shown, by way of the conductor C541, the contacts 572 of the reverting call key K570, C547, the contacts 534, the line conductor C521 of the trunk 520, the wiper 383 and engaged contact in the associated contact bank 384 of the sequence switch 380, the line conductor C324, the contacts 355 and 335, the wiper 315, C274 and the contacts 254 and 249 to the line conductor C272 of the telephone line 270 and from the other terminal of the source of ringing current, not shown, by way of the conductor C542, the contacts 571 of the reverting call key K570, C548, the contacts 532, the line conductor C522 of the trunk 520, the wiper 385 and engaged contact in the associated contact bank 386 of the sequence switch 380, the line conductor C322, the contacts 352 and 333, the wiper 314, C277 and the contacts 251 and 246 to the line conductor C271 of the telephone line 270, the ringers at the subscriber substations T₂ and T₃ being connected across the line conductors of the telephone line 270. Accordingly the ringers at the subscriber substations T₂ and T₃ are operated at this time. At this point it is noted that code ringing may be utilized and that a code selector switch may be interposed between the source of ringing current and the line 540 extending thereto, whereby different codes of ringing current may be transmitted over the telephone line 270 in order selectively to control the operation of the ringers at the subscriber substations T₂ and T₃. Further it is noted that while the telephone line 270 is being rung over the finder switch 300 the selector switch 400 is retained in its operated position due to the completed loop circuit between the line relay R455 in the selector switch 400 and the retarder coil 530 connected across the line conductors C523 and C524 of the trunk 520 at this time.

After operating the reverting call key K570 in order to cause ringing current to be projected over the telephone line 270, the operator at the first A operator position 500 restores the reverting call key K570 to its normal position, thereby to interrupt, at the contacts 573 thereof, the 75

previously mentioned circuit for energizing the winding of the rear split relay R530 and to interrupt, at the contacts 571 and 572 thereof, the previously traced circuit for projecting ringing current over the telephone line 270. The rear split relay R530 then restores, thereby to recomplete, at the contacts 531 and 533, the previously traced loop circuit between the repeater 501 and the calling subscriber substation T₂, assuming that the subscriber at the calling subscriber substation T₂ has removed the receiver of the telephone instrument thereat from its switchhook at this time. Further assuming that the subscriber at the called subscriber substation T₃ has answered the call by removing the receiver of the telephone instrument thereat from its switchhook at this time, an established connection is completed between the calling subscriber substation T₂ and the called subscriber substation T₃. Also the connection between the telephone line 270 and the first A operator position 500 is recompleted at this time. Accordingly, the operator at the first A operator position 500 may converse with the subscribers at the subscriber substations T₂ and T₃ advising them to proceed with the conversation.

The operator at the first A operator position 500 then operates the permanent lockout release key K555, thereby to complete, at the contacts 557 thereof, an obvious circuit for energizing the winding of the front split relay R535 and to complete, at the contacts 556 thereof, a path for connecting ground potential to the line conductor C361 of the trunk 360 upon operation of the front split relay R535. Upon operating the front split relay R535 interrupts, at the contacts 538, the previously traced loop circuit extending between the line relay R455 in the selector switch 400 and the repeater 501. However, at this time, an alternative circuit is completed for energizing in series the upper winding of the error relay R450 and the upper winding of the line relay R455, this circuit extending from ground by way of the contacts 556 of the permanent lockout release key K555, the contacts 537 and 542, the line conductor C523 of the trunk 520, the wiper 389 and engaged contact in the associated contact bank 390 of the sequence switch 380, the line conductor C321, the contacts 351, the line conductor C361 of the trunk 360, the upper winding of R450 and the upper winding of R455 to battery. Accordingly the line relay R455 remains in its operated position; while the error relay R450 operates, the lower winding thereof being short-circuited at this time. Upon operating the error relay R450 completes, at the contacts 451, a circuit for energizing the winding of the lockout relay R425, this circuit extending from direct ground by way of the contacts 556 of the permanent lockout release key K555 over the previously traced path to the line conductor C361 of the trunk 360 and therefrom by way of the contacts 451 and the winding of R425 to battery. When thus energized the lockout relay R425 operates to interrupt, at the contacts 427, the previously traced path for applying ground potential to the control conductor C363 of the trunk 360 and to complete, at the contacts 426, a path for applying booster battery potential to the control conductor C363 of the trunk 360. The path for applying booster battery potential to the control conductor C363 of the trunk 360 extends from ground by way of the booster battery 424 and the contacts 426 to the control conductor C363. This application of booster battery

potential to the control conductor C363 of the trunk 360 completes an alternative holding circuit substantially identical to that previously traced for energizing the intermediate winding of the switching relay R320 and completes a circuit for effectively energizing the lockout relay R250 in the two-party line register circuit 240 individually associated with the telephone line 270. The circuit for energizing the winding of the lockout relay R250 extends from booster battery potential appearing on the control conductor C363 of the trunk 360 by way of the contacts 337, the wiper 316, the control conductor C215 of the telephone line 270, the contacts 283, the resistor 258 and the winding of R250 to battery. When thus energized the lockout relay R250 operates to complete, at the contacts 252 and 253, a holding circuit for energizing the winding thereof, this circuit extending from ground by way of the contacts 252 and 246, C211, the bridge paths at the subscriber substations T2 and T3 between the line conductors C211 and C272 of the telephone line 270, C272, the contacts 249 and 253 and the winding of R250 to battery. Also the lockout relay R250 completes, at the contacts 255, an obvious path for applying ground potential to the control conductor C273 of the telephone line 270, thereby to mark the telephone line 270 as busy to the B operator positions having access thereto. Further the lockout relay R250 completes, at the contacts 257, an obvious circuit for illuminating the permanent signal lamp L243. The illumination of the permanent signal lamp L243 indicates to the operators at the A operator positions that the telephone line 270 is locked out of service at this time. Finally the lockout relay R250 interrupts, at the contacts 251 and 254, the previously traced loop circuit between the subscriber substations T2 and T3 and the repeater 501.

After the permanent signal lamp L243 is illuminated, in order to indicate to the operator at the first A operator position 500 that the telephone line 270 is locked out of service the operator at the first A operator position 500 restores the permanent lockout release key K555 to its normal position, thereby to interrupt, at the contacts 557 thereof, the previously mentioned circuit for energizing the winding of the front split relay R535 and to interrupt, at the contacts 558 thereof, the previously traced circuit for energizing in series the upper winding of the error relay R450 and the upper winding of the line relay R455. Accordingly the front split relay R535 restores to complete, at the contacts 536 and 538, the previously traced loop circuit between the line relay R455 in the selector switch 400 and the repeater 501, thereby to cause the error relay R450 to restore. Upon restoring the error relay R450 interrupts, at the contacts 451, the previously traced circuit for energizing the winding of the lockout relay R425, thereby to cause the latter relay to restore. Upon restoring the lockout relay R425 interrupts, at the contacts 426, the previously traced path for applying booster battery potential to the control conductor C363 of the trunk 360 and completes, at the contacts 427, the previously traced path for applying ground potential to the control conductor C363 of the trunk 360. Accordingly at this time, only the loop circuit extending between the line relay R455 in the selector switch 400 and the repeater 501 is completed.

The operator at the first A operator position 500 then momentarily operates the transfer key K565 and then returns this key to its normal po-

sition. When the transfer key K565 is thus momentarily operated the previously traced holding circuit for energizing in series the winding of the hold relay R630 in the A operator position distributor 630 and the upper winding of the cutin relay R350 in the finder switch 300 is interrupted, thereby to cause the hold relay R630 and the cutin relay R350 to restore. Upon restoring the cutin relay R350 interrupts, at the contacts 351 and 354, the previously traced loop circuit between the line relay R455 in the selector switch 400 and the repeater 501, thereby to cause the line relay R455 to restore. The restoration of the line relay R455 effects the release of the finder switch 300 and the selector switch 400, in the manner previously explained. Accordingly, at this time the link illustrated and the first A operator position 500 are completely released while the telephone line 270 is locked out of service.

When the subscribers at the subscriber substations T2 and T3 replace the receivers of the respective telephone instruments thereat upon their switchhooks the bridge paths between the line conductors C211 and C272 of the telephone line 270 are interrupted, thereby to interrupt the previously traced holding circuit for energizing the winding of the lockout relay R250. The lockout relay R250 then restores, thereby to cause the two-party line register circuit 240 to place the telephone line 270 again in service. Further the lockout relay R250 interrupts, at the contacts 257, the previously mentioned circuit for illuminating the permanent signal lamp L243, thereby to cause the signal lamp L243 to be extinguished in order to indicate to the operators at the A operator positions that the telephone line 270 is no longer locked out of service. Finally the lockout relay R250 interrupts, at the contacts 255, the previously mentioned path for applying ground potential to the control conductor C273 of the telephone line 270 and completes, at the contacts 256, the previously traced path for applying battery potential by way of the intermediate winding of the line and cutoff relay R260 to the control conductor C273 of the telephone line 270, thereby to mark the telephone line 270 as idle.

In connection with the operation of the two-party line register circuit 240 it is noted that in the event a permanent fault appears upon the telephone line 270 the two-party line register circuit 240 operates in order to create a call upon the telephone line 270 in the manner previously described, thereby to initiate operation of the distributor 301. The distributor 301 then assigns a previously selected link to the use of the calling telephone line 270, such, for example, as the link illustrated, whereupon the finder switch 300 operates to seize the telephone line 270 in the manner previously explained. Also the sequence switch 380 operates to seize the trunk extending to an idle one of the A operator positions assigned for use, such, for example, as the first A operator position 500, thereby to cause the call to be routed by the finder switch 300 to the first A operator position 500. When the operator at the first A operator position 500 challenges the line 270 and is unable to communicate with either the subscriber at the subscriber substation T2 or the subscriber at the subscriber substation T3, she concludes that a permanent fault is present on the telephone line 270. The operator at the first A operator position 500 then proceeds to cause the two-party line register circuit 240 to operate in order to lock the telephone line 270 out of service by operating the permanent lockout release key

K555, in the manner previously explained. The operator at the first A operator position 500 then operates the transfer key K565 in order to cause the finder switch 300, the selector switch 400 and the first A operator position 500 to be released, as previously explained. At this time the line 270 remains locked out of service until the fault thereon is removed, thereby to cause the previously traced holding circuit for energizing the winding of the lockout relay R250 to be interrupted. The lockout relay R250 then restores, thereby again to place the telephone line 270 in service, in the manner previously explained.

Paystation call

A call from a paystation, such, for example, as the paystation T4, is initiated by removing the receiver of the telephone instrument thereat from its switchhook and depositing a coin in the coin slot of the telephone instrument thereat. When the receiver of the telephone instrument at the paystation T4 is removed from its switchhook and the coin is deposited in the coin slot of the telephone instrument thereat, a bridge path is completed between the line conductors C286 and C287 of the telephone line 285 extending to the paystation T4 and the prepay manual line circuit 280 individually associated with the telephone line 285 is operated in order to cause battery potential to be applied to the control conductor C288 of the telephone line 285, to cause direct ground potential to be applied to the control conductor C289 of the telephone line 285 and to cause ground potential to be applied to the start conductor C291. The application of ground potential to the start conductor C291 completes an obvious path for applying ground potential by way of the resistor 302 of the marking network 305 to the start conductor C308 extending to the distributor 301, and an obvious path for applying direct ground potential to the third contacts in the vertical control contact banks of the finder switches. The application of ground potential to the start conductor C308 initiates operation of the distributor 301 and the application of direct ground potential to the third contacts in the vertical control contact banks of the finder switches marks the telephone line 285 as terminating in the third level of the main contact banks of the finder switches.

The finder distributor 301 then operates to cause the previously selected link to be assigned to the use of the calling paystation T4, in the previously described manner. Assuming that the distributor 301 operates to assign the link illustrated to the use of the calling paystation T4, the finder switch 300 operates in the manner previously described to seize the telephone line 285 extending to the calling paystation T4. Also the selector switch 400 and the sequence switch 380 operate in the manners previously described. Assuming that the A operator position distributor 630 has previously selected the first A operator position 500 for use at this time, the sequence switch 380 operates to seize the trunk 520 extending to the first A operator position 500, in the manner previously explained.

When the first A operator position 500 is seized by the sequence switch 380 the cutin relay R350 operates in order to complete, at the contacts 351 and 354, the previously traced loop circuit between the line relay R455 in the selector switch 400 and the repeater 501, and to complete, at the contacts 352 and 355, a loop circuit between the calling paystation T4 and the repeater 501. This

loop circuit extends from the line conductor C286 of the telephone line 285 by way of the wiper 314, the contacts 333 and 352, the line conductor C322, the wiper 385 and engaged contact in the associated contact bank 386 of the sequence switch 380, the line conductor C522 of the trunk 520, the contacts 531 and 516, the windings 503 and 504 of the repeater 501, the condenser 509, the contacts 533, the line conductor C521 of the trunk 520, the wiper 383 and engaged contact in the associated contact bank 384 of the sequence switch 380, the line conductor C324, the contacts 355 and 335, and the wiper 315 to the line conductor C287 of the telephone line 285, the line conductors C286 and C287 of the telephone line 285 being connected together by way of the bridge path at the calling paystation T4.

Also, when the finder switch 300 seizes the telephone line 285 direct ground potential is applied by way of the wiper 316 to the control conductor C288 of the telephone line 285, thereby to cause the prepay manual line circuit 280 individually associated with the telephone line 285 to operate and free the line conductors C286 and C287 of the telephone line 285 of impedance elements. Also the prepay manual line circuit 280 operates to interconnect the control conductors C288 and C290 of the telephone line 285, thereby to cause ground potential to be applied to the control conductor C290 of the telephone line 285 in order to mark the telephone line 285 as busy to the B operator positions having access thereto.

Finally the cutin relay R350 completes, at the contacts 357, a series circuit for energizing the windings of the signal relays R685 and R690, this circuit extending from ground in the prepay manual line circuit 280 by way of the control conductor C289 of the telephone line 285, the wiper 317, the contacts 357, the control conductor C325, the wiper 381 and engaged contact in the associated contact bank 382 of the sequence switch 380, the control conductor C525 of the trunk 520, the contacts 562 of the control key K560, the contacts 592 of the second register key K590, the contacts 597 of the first register key K595, and the windings of R685 and R690 to battery. When this low resistance series circuit is completed for energizing the windings of the signal relays R685 and R690 both of these signal relays operate, thereby to complete, at the contacts 681 and 692, a circuit for illuminating the prepay signal lamp L682, this circuit extending from ground by way of the contacts 631, 687 and 692 and the prepay signal lamp L682 to battery. The illumination of the prepay signal lamp L682 indicates to the operator at the first A operator position 500 that the call being answered was initiated at a telephone station which is rendered prepay manual service and that the coin deposited in the coin slot of the telephone instrument at the paystation T4 should be either collected or returned to the subscriber thereat.

The operator at the first operator position 500 then answers the call and is advised concerning the extension of the call by the subscriber at the calling paystation T4. The extension of the call from the first A operator position 500 to a called operator position, such, for example, as the first B operator position 494, and the subsequent completion of a direct connection between the paystation T4 and the first B operator position 494 are the same as previously described. Furthermore, the release of the established connection between the calling paystation T4 and the first

B operator position 494 is the same as that previously described.

In the present instance, the operator at the first A operator position 500 does not operate the transfer key K565 at her position in order to complete a direct connection between the calling paystation T4 and the first B operator position 494 until after the operator at the first B operator position 494 extends the call to the called subscriber substation in the local exchange 20 and determines whether the call can be completed at this time. In the event the operator at the first B operator position 494 is able to complete the connection to the called subscriber substation at this time, the operator at the first A operator position 500 operates the coin collect key K580 before operating the transfer key K565. On the other hand, in the event the operator at the first B operator position 494 is not able to complete the connection to the called subscriber substation at this time, the subscriber at the calling paystation T4 is so advised by the operator at the first A operator position 500 and the coin return key K585 is operated at the first A operator position 500 before operating the transfer key K565.

When the coin collect key K580 is operated there is completed, at the contacts 583 thereof, an obvious circuit for energizing the winding of the rear split relay R530, thereby to cause the latter relay to operate and complete, at the contacts 532 and 534, an alternative loop circuit between the calling paystation T4 and the coin collect key K580. This loop circuit extends from the line conductor C521 of the trunk 520 by way of the contacts 534, C547, the contacts 582 of the coin collect key K580, C546 and the contacts 532 to the line conductor C522 of the trunk 520, the line conductors C521 and C522 of the trunk 520 being connected to the calling paystation T4 by way of the previously traced circuit. Also, at the contacts 581 of the coin collect key K580, a path is completed for connecting positive 110 volt D. C. potential to the line conductors C286 and C287 of the telephone line 285, this path extending from a source of positive 110 volt D. C. potential by way of the conductor C553, the contacts 581 of the coin collect key K580 to the conductors C546 and C547 and therefrom by way of the contacts 532 and 534 and the line conductors C522 and C521 of the trunk 520 and the previously traced circuit to the line conductors C286 and C287 of the telephone line 285. The application of positive 110 volt D. C. potential to the line conductors C286 and C287 of the telephone line 285 causes the coin control apparatus at the paystation T4 to operate and collect the coin deposited in the coin slot of the telephone instrument thereat.

Subsequently, the coin collect key K580 is returned to its normal position, thereby to interrupt, at the contacts 583, the previously mentioned circuit for energizing the winding of the rear split relay R530, to interrupt, at the contacts 582, the previously traced connection between the line conductors C286 and C287 of the telephone line 285, and to interrupt, at the contacts 581 thereof, the previously traced path for applying positive 110 volt D. C. potential to the line conductors C286 and C287 of the telephone line 285. The rear split relay R530 then restores, thereby to recomplete the loop circuit between the calling paystation T4 and the repeater 501. Subsequently the operator at the first A operator position 500 operates the transfer key K565, thereby to complete the direct loop circuit between the

paystation T4 and the line relay R455 in the selector switch 400.

When the coin return key K585 is operated there is completed, at the contacts 588 thereof, an obvious circuit for energizing the winding of the rear split relay R530, thereby to cause the latter relay to operate and complete, at the contacts 532 and 534, an alternative loop circuit between the calling paystation T4 and the coin return key K585. This loop circuit extends from the line conductor C521 of the trunk 520 by way of the contacts 534, C547, the contacts 587 of the coin return key K585, C546 and the contacts 532 to the line conductor C522 of the trunk 520, the line conductors C521 and C522 of the trunk 520 being connected to the calling paystation T4 by way of the previously traced circuit. Also, at the contacts 586 of the coin return key K585, a path is completed for connecting negative 110 volt D. C. potential to the line conductors C286 and C287 of the telephone line 285, this path extending from a source of negative 110 volt D. C. potential by way of the conductor C554, the contacts 586 of the coin return key K585, to the conductors C546 and C547 and therefrom by way of the contacts 532 and 534 and the line conductors C522 and C521 of the trunk 520 and the previously traced circuit to the line conductors C286 and C287 of the telephone line 285. The application of negative 110 volt D. C. potential to the line conductors C286 and C287 of the telephone line 285 causes the coin control apparatus at the paystation T4 to operate and return the coin deposited in the coin slot of the telephone instrument thereat.

Subsequently, the coin return key K585 is returned to its normal position, thereby to interrupt, at the contacts 588, the previously mentioned circuit for energizing the winding of the rear split relay R530, to interrupt, at the contacts 587, the previously traced connection between the line conductors C286 and C287 of the telephone line 285, and to interrupt, at the contacts 588 thereof, the previously traced path for applying negative 110 volt D. C. potential to the line conductors C286 and C287 of the telephone line 285. The rear split relay R530 then restores, thereby to recomplete the loop circuit between the calling paystation T4 and the repeater 501. Subsequently the operator at the first A operator position 500 operates the transfer key K565, thereby to cause the link illustrated to be released, assuming that the subscriber at the calling paystation T4 has replaced the receiver of the telephone instrument thereat upon its switchhook at this time.

Call and recall storage

In a previous explanation of the operation of the system it was assumed that the A operator position distributor 630 had previously selected an idle A operator position when the calls were initiated at the subscriber substations T1, T2 and T3 and at the paystation T4, and when the recall was initiated at the first B operator position 494. However, it may occur that all of the A operator positions are busy when one or more calls are initiated at the subscriber substations or paystations, or when one or more recalls are initiated at the various called operator positions. More particularly, when all of the A operator positions are busy the corresponding hold relays R630, R640, R645, etc., occupy their operated positions, thereby to retain interrupted, at the re-

spective contacts 638, 641, 646, etc., the paths for applying ground potential to the control conductor C672 and to retain prepared, at the respective contacts 635, 642, 647, etc., the circuits for energizing the left-hand windings of the respective position relays R660, R665, R650, etc. Accordingly, at this time the position relays R650, R660 and R665 operate and restore in sequence in order sequentially to test the corresponding A operator positions and continue to operate automatically in sequence until an idle A operator position is tested and thus selected for use. For example, when all of the hold relays R630, R640, R645, etc., are operated and the position relay R650 operates it completes, at the contacts 651, the previously traced circuit for energizing the left-hand winding of the position relay R660, thereby to cause the latter relay to operate. Upon operating the position relay R660 completes, at the contacts 663, the previously mentioned circuit for energizing the left-hand winding of the position relay R665, thereby to cause the latter relay to operate. Upon operating the position relay R665 completes, at the contacts 667, the previously mentioned circuit for energizing the left-hand winding of the position relay R650, thereby to cause the latter relay to operate. When each of the position relays operates it interrupts the holding circuit of the preceding position relay and completes the operating circuit of the succeeding position relay, a series holding circuit for the right-hand winding of one of the position relays and the winding of the control relay R670 being completed at any particular time.

Assuming that one or more calls are initiated in sequence at this time when all the A operator positions are busy, the sequence switch associated with the first link taken for use will operate in the previously described manner until the wiper thereof engages the seventh contact in the associated contact bank, or occupies a setting corresponding to the first storage setting of the call storage unit 600, whereupon a series circuit is completed for energizing the winding of the marking relay 1M and the upper winding of the cutin relay in the associated finder switch of the first link, thereby to cause operation of the marking relay 1M shortly thereafter, this relay being of the slow-to-operate type, and operation of the cutin relay in the finder switch of the associated first link. The operation of the cutin relay in the finder switch of the first link arrests operation of the associated sequence switch in the manner previously explained; and the operation of the marking relay 1M completes, at the contacts 1M1, a path for applying battery potential by way of the winding of the marking relay 2M to the marking conductor C535. Also the marking relay 1M prepares, at the contacts 1M2, the previously traced series circuit for energizing the windings of the release relay R620 and the control relay R610; however, this series circuit is not completed at this time due to the operated condition of all of the hold relays R630, R640, R645, etc. Finally the marking relay 1M completes, at the contacts 1M3, an obvious circuit for illuminating the storage signal lamp L601. The illumination of the storage signal lamp L601 indicates to the operators at the A operator positions that a call is stored in the first position 70 or setting of the call storage unit 600.

The sequence switch associated with the second link taken for use will operate in the previously described manner until the wiper thereof engages the sixth contact in the associated con-

tact bank, whereupon a series circuit is completed for energizing the winding of the marking relay 2M and the upper winding of the cutin relay in the associated finder switch of the second link, thereby to cause operation of the marking relay 2M shortly thereafter, this relay being of the slow-to-operate type, and operation of the cutin relay in the finder switch of the associated second link. The operation of the cutin relay in the finder switch of the second link arrests operation of the associated sequence switch in the manner previously explained; and the operation of the marking relay 2M completes, at the contacts 2M1, a path for applying battery potential by way of the winding of the marking relay 3M to the marking conductor C534. Finally the marking relay 2M completes, at the contacts 2M2, an obvious circuit for illuminating the storage signal lamp L602. The illumination of the storage signal lamp L602 indicates to the operators at the A operator positions that a call is stored in the second position of the call storage unit 600.

In view of the foregoing explanation of the manner in which the first and second calls initiated at a time when all of the A operator positions are busy are stored in the first and second positions of the call storage unit 600, respectively corresponding to the marking relays 1M and 2M, it will be understood that the third, fourth, fifth and sixth calls initiated at this time will be stored in the respective third, fourth, fifth and sixth storage positions of the call storage unit 600 corresponding to the marking relays 3M, 4M, 5M and 6M. Further it will be understood that, upon operating, the marking relays 3M, 4M, 5M and 6M respectively and sequentially complete the circuits for illuminating the storage signal lamps L603, L604, L605 and L606. Finally upon operating, the marking relay 6M completes, at the contacts 6M1, a path for applying battery potential by way of the resistor 670 to the marking conductor C530, thereby to cause the sequence switch associated with each of the links in addition to the previously mentioned six to be arrested when the wiper engages the first contact in the associated contact bank, thereby to cause the remainder of the calls initiated at this time to be conserved until there is storage facility in the call storage unit 600.

In view of the foregoing explanation of the operation of the call storage unit 600, it will be understood that all incoming calls and recalls are routed in a predetermined order to idle ones of the A operator positions when one or more of the A operator positions are idle; when all of the A operator positions are busy the next six calls and recalls initiated are stored in order in the respective six storage positions of the call storage unit 600; and when all of the storage positions in the call storage unit 600 are occupied, subsequent calls and recalls are conserved until there is storage facility in the call storage unit 600.

Continuing now with the operation of the call storage unit, it is assumed that one or more of the A operator positions become idle at this time. When the A operator position becomes idle at this time, the corresponding hold relay restores, thereby to cause operation of the A operator position distributor 630 to be arrested and the idle A operator position to be selected by the A operator position distributor 630 for use. When the idle A operator position is selected for use by the A operator position distributor 630, ground potential is applied to the control conductor C672, thereby to complete the previously traced series circuit

for energizing the windings of the release relay R620 and the control relay R610, whereupon the release relay R620 operates immediately and the control relay R610 operates shortly thereafter. Upon operating the release relay R620 interrupts, at the contacts 621, the previously traced series circuit for energizing the marking relay 1M and the upper winding of the cutin relay in the finder switch of the first link, thereby to cause the marking relay 1M and the cutin relay mentioned to restore. Upon restoring the cutin relay in the finder switch of the first link initiates further operation of the sequence switch associated with the first link, whereupon this sequence switch operates to find the trunk extending to the idle A operator position, in the manner previously explained.

Also the marking relay 1M restores, thereby to interrupt, at the contacts 1M1, the previously traced series circuit for energizing the winding of the marking relay 2M and the upper winding of the cutin relay in the finder switch of the second link, thereby to cause the marking relay 2M and the cutin relay mentioned to restore. When the cutin relay in the finder switch of the second link restores, further operation of the associated sequence switch is initiated, whereupon the sequence switch operates to cause the wiper to engage the seventh contact in the associated contact bank terminating the marking conductor C536, thereby to cause a series circuit for energizing the upper winding of the cutin relay in the finder switch of the second link and the winding of the marking relay 1M to be completed. The cutin relay in the finder switch of the second link operates to arrest further operation of the associated sequence switch; while the marking relay 1M operates to cause reoperation of the release relay R620 and the control relay R610, in the event there is an idle A operator position selected by the A operator position distributor 630 at this time.

On the other hand, in the event there is no idle A operator position selected by the A operator position distributor 630 at this time, the release relay R620 and the control relay R610 are not reoperated. Hence, the sequence switch associated with the second link is not operated further at this time. Accordingly, the marking relay 1M restores and subsequently reoperates. The restoration of the marking relay 1M causes sequential restoration of the marking relays 2M, 3M, 4M, 5M and 6M, thereby to initiate sequential operations of the sequence switches associated with the second, third, fourth, fifth and sixth links. Upon reoperating, the marking relay 1M reprepares, at the contacts 1M1, the previously traced path for applying battery potential by way of the winding of the marking relay 2M to the marking conductor C535, thereby to cause the sequence switch associated with the third link to be arrested when the wiper thereof engages the sixth contact in the associated contact bank. The marking relay 2M then operates to prepare, at the contacts 2M1, the previously traced path for applying battery potential by way of the winding of the marking relay 3M to the marking conductor C534. In view of the above explanation the restoration and subsequent operation of each of the marking relays 1M to 6M, inclusive, it will be understood that the first link occupying the first storage position in the call storage unit 600 is operated to find the idle A operator position, while the sequence switches associated with the second, third, fourth, fifth and

sixth links respectively occupying the second, third, fourth, fifth and sixth storage positions in the call storage unit 600 are advanced one position in order respectively to occupy the first, second, third, fourth and fifth storage positions of the call storage unit 600.

Further it is noted that when the marking relay 6M restores it interrupts, at the contacts 6M1, the previously traced path for applying battery potential to the marking conductor C530, thereby to cause the sequence switches associated with the seventh, eighth, etc., links to operate further, whereupon the wiper of the sequence switch associated with one of the seventh, eighth, etc., links engages the second contact in the associated contact bank, thereby to cause subsequent operation of the sequence switch associated with the last mentioned link to be arrested. Accordingly, at this time the call on the last mentioned link is stored in the sixth position of the call storage unit 600; and the sequence switches associated with the remainder of the links continue to operate until the wipers thereof reengage the first contacts in the associated contact banks, thereby to cause the calls on the remainder of the links to be conserved until there is storage facility in the call storage unit 600.

In view of the foregoing explanation of the operation of the call storage unit 600, in order to release calls from storage it will be understood that the call stored in the first position of the call storage unit 600 is first released and the remainder of the calls stored are advanced one position. Accordingly, calls are stored in the call storage unit 600 when all of the A operator positions are busy, in a predetermined order, and are released as the A operator positions become idle in the same predetermined order. Furthermore, all incoming calls are conserved to be stored later when all of the storage facility of the call storage unit 600 is utilized and are subsequently advanced to call storage positions indiscriminately. Hence, the unit 600 comprises not only a call storage unit, but also a call storage distributor.

CONCLUSIONS

From the foregoing it is apparent that a telephone system is provided which comprises an exchange including a number of operator positions and an improved distributor arrangement for routing, in a predetermined order, incoming calls and recalls to the exchange to the operator positions to be answered. Also the exchange embodies an improved call storage arrangement for storing, in a predetermined order, incoming calls and recalls to the exchange when all of the operator positions are busy and for subsequently releasing the stored calls and recalls in the same predetermined order to the operator positions to be answered as the operator positions become idle.

While there has been described what is at present considered to be the preferred embodiment of the invention, it will be understood that various modifications may be made therein and it is intended to cover in the appended claims all such modifications as fall within the true spirit and scope of the invention.

What is claimed is:

1. In a telephone system, a plurality of subscriber lines, a plurality of A operator positions, a B operator position, means for establishing a connection between a calling one of said subscriber lines and an idle one of said A operator

position, thereby to route a call from said one subscriber line to said B operator position, means for routing a recall by an operator at said B operator position upon said established connection to an idle one of said A operator positions to be answered when one of said A operator positions is idle, means for routing a recall upon said established connection to said storage unit to be stored when all of said A operator positions are busy, and means for routing a recall upon said established connection stored in said storage unit to an idle one of said A operator positions to be answered when one of said A operator positions becomes idle.

9. In a telephone system, a plurality of subscriber lines, a plurality of A operator positions, a B operator position, a storage unit, means for routing a call upon any one of said subscriber lines to said storage unit to be stored, means for routing a call upon said one subscriber line stored in said storage unit to an idle one of said A operator positions to be answered, means for routing a call from said one A operator position to said B operator position, means for establishing a connection between said one subscriber line and said B operator position independent of said one A operator position, thereby to route a call from said one subscriber line to said B operator position.

10. In a telephone system, a plurality of subscriber lines, a plurality of A operator positions, a B operator position, a storage unit, means for routing a call upon any one of said subscriber lines to an idle one of said A operator positions to be answered when one of said A operator positions is idle, means for routing a call upon said one subscriber line to said storage unit to be stored when all of said A operator positions are busy, means for routing a call upon said one subscriber lines stored in said storage unit to an idle one of said A operator positions to be answered when one of said A operator positions becomes idle, means for routing a call from said one A operator position to said B operator position, means for establishing a connection between said one subscriber line and said B operator position independent of said one A operator position, thereby to route a call from said one subscriber line to said B operator position.

11. In a telephone system, a plurality of lines, a plurality of operator positions, a link including an answer switch having access to said lines and a finder switch having access to said operator positions, means controlled by the presence of a call on any one of said lines for initiating substantially simultaneous operations of said answer switch and said finder switch, means controlled when said answer switch finds a calling one of said lines for arresting operation of said answer switch, thereby to extend a call from said one line to said link, and means controlled when said finder switch finds an idle one of said operator positions for arresting operation of said finder switch, thereby to extend a call from said link to said one operator position to be answered.

12. In a telephone system, a plurality of lines, a plurality of operator positions, a link including an answer switch having access to said lines and a call switch and a finder switch having access to said operator positions, means controlled by the presence of a call on any one of said lines for initiating substantially simultaneous operations of said answer switch and said finder switch, means controlled when said an-

swer switch finds a calling one of said lines for arresting operation of said answer switch, thereby to extend a call from said one line to said link, means controlled when said finder switch finds an idle one of said operator positions for arresting operation of said finder switch, thereby to extend a call from said link to said one operator position to be answered, and means under the control of an operator at said one operator position for selectively operating said call switch, thereby to extend a call from said one operator position.

13. In a telephone system, a plurality of lines, a plurality of operator positions, a storage unit having a number of storage settings, a link including an answer switch having access to said lines and a finder switch having access to said operator positions and to the storage settings of said storage unit, means controlled by the presence of a call on any one of said lines for initiating operations of said answer switch and said finder switch, means controlled when said answer switch finds a calling one of said lines for arresting operation of said answer switch, thereby to extend a call from said one line to said link, means controlled when said finder switch finds an idle one of said operator positions or a prepared one of the storage settings of said storage unit for arresting operation of said finder switch, thereby to extend a call on said link to said one operator positions to be answered or to store a call on said link in said one storage setting of said storage unit, and means for preparing the storage settings of said storage unit in a predetermined order when all of said operator positions are busy.

14. In a telephone system, a plurality of lines, a plurality of operator positions, a storage unit having a number of storage settings, a link including an answer switch having access to said lines and a finder switch having access to said operator positions and to the storage settings of said storage unit, means controlled by the presence of a call on any one of said lines for initiating operations of said answer switch and said finder switch, means controlled when said answer switch finds a calling one of said lines for arresting operation of said answer switch, thereby to extend a call from said one line to said link, means controlled when said finder switch finds an idle one of said operator positions or a prepared one of the storage settings of said storage unit for arresting operation of said finder switch, thereby to extend a call from said link to said one operator position to be answered or to store a call on said link in said one storage setting of said storage unit, means for preparing the storage settings of said storage unit in a predetermined order when all of said operator positions are busy, and additional means controlled when one of said operator positions becomes idle for initiating reoperation of said finder switch.

15. In a telephone system, a plurality of lines, a link including an answer switch having access to said lines and a call switch, means controlled by the presence of a call on any one of said lines for causing the answer switch of said link to seize said one line, thereby to extend the call to said link, an operator position, a storage unit, means for routing a call on said link to said operator position to be answered when said operator position is idle, means for routing a call on said link to said storage unit to be stored when said operator position is busy, means for routing a call on said link stored in said storage unit to

said operator position to be answered when said operator position becomes idle, and means under the control of an operator at said operator position for governing the operation of the call switch of said link, thereby to extend the call from said operator position.

16. In a telephone system, a plurality of lines, a link including an answer switch having access to said lines and a call switch, means controlled by the presence of a call on any one of said lines for causing the answer switch of said link to seize said one line, thereby to extend the call to said link, a plurality of operator positions, a storage unit, means for routing a call on said link to an idle one of said operator positions to be answered when one of said operator positions is idle, means for routing a call on said link to said storage unit to be stored when all of said operator positions are busy, means for routing a call on said link stored in said storage unit to an idle one of said operator positions to be answered when one of said operator positions becomes idle, and means under the control of an operator at any one of said operator positions to which the call on said link is routed for governing the operation of the call switch of said link, thereby to extend the call from said one operator position.

17. In a telephone system, a plurality of lines, a plurality of links each including an answer switch having access to said lines and a call switch, means controlled by the presence of calls on said lines for assigning said links for use in a predetermined order and for causing the answer switches of said assigned links to seize said lines having calls thereon, thereby to extend the calls on said lines to said assigned links, a plurality of operator positions, a storage unit, means for routing the calls on said assigned links to idle ones of said operator positions, to be answered when said operator positions are idle, means for routing the calls on said assigned links to said storage unit to be stored when all of said operator positions are busy, means for routing the calls on said assigned links stored in said storage unit to idle ones of said operator positions to be answered when said operator positions become idle, and means under the control of an operator at any one of said operator positions to which the call on any one of said assigned links is routed for governing the operation of the call switch of said one assigned link, thereby to extend the call from said one operator position.

18. In a telephone system, a first group of lines, a second group of lines, a plurality of operator positions, a plurality of links each including an answer switch having access to said first group of lines and a call switch having access to said second group of lines and switching apparatus having access to said operator positions, means including a link distributor for assigning said links in a predetermined order and for causing the answer switch of an assigned link to seize a calling line in said first group of lines, thereby to extend the call on said calling line to said assigned link, means including a position distributor for assigning said operator positions in a predetermined order and for causing the switching apparatus of said assigned link to seize an assigned operator position, thereby to extend the call on said assigned link to said assigned operator position, and means under the control of an operator at said assigned operator position for causing the call switch of said assigned link to seize a called line in said second group of lines, thereby to extend the call on said assigned link to said called line.

19. In a telephone system, a plurality of lines, a link including a first branch provided with an answer switch having access to said lines and a second branch provided with a call switch, means controlled by the presence of a call on any one of said lines for causing the answer switch of said link to seize said one line, thereby to extend the call to said link, an operator position including telephone apparatus, a storage unit, means for routing a call on said link to said operator position to be answered when said operator position is idle, means for routing a call on said link to said storage unit to be stored when said operator position is busy, means for routing a call on said link stored in said storage unit to said operator position to be answered when said operator position becomes idle, means under the control of an operator at said operator position for governing the operation of the call switch of said link, thereby to extend the call from said operator position, means at said operator position for completing a three-way communication connection including the telephone apparatus thereat and the first and the second branches of said link, and means under the control of an operator at said operator position for completing a communication connection between the first and the second branches of said link independent of said operator position.
20. In a telephone system, a plurality of lines, a link including a first branch provided with an answer switch having access to said lines and a second branch provided with a call switch, means controlled by the presence of a call on any one of said lines for causing the answer switch of said link to seize said one line, thereby to extend the call to said link, a plurality of operator positions each including telephone apparatus, a storage unit, means for routing a call on said link to an idle one of said operator positions to be answered when one of said operator positions is idle, means for routing a call on said link to be stored when all of said operator positions are busy, means for routing a call on said link stored in said storage unit to an idle one of said operator positions to be answered when one of said operator positions becomes idle, means under the control of an operator at any one of said operator positions to which the call on said link is routed for governing the operation of the call switch of said link, thereby to extend the call from said one operator position, means at said operator position for completing the telephone apparatus thereat and the first and the second branches of said link, and means under the control of an operator at any one of said operator positions to complete a communication connection between the first and the second branches of said link independent of said operator position.
21. In a telephone system, a plurality of lines, a plurality of links each including a first branch provided with an answer switch having access to said lines and a second branch provided with a call switch, means controlled by the presence of calls on said lines for assigning said links for use in a predetermined order and for causing the answer switches of said assigned links to seize said lines having calls thereon, thereby to extend the calls on said lines to said assigned links, a plurality of operator positions each including telephone apparatus, a storage unit, means for routing the calls on said assigned links to idle ones of said operator positions to be answered when one of said operator positions is idle, means under the control of an operator at any one of said operator positions to which the call on said link is routed for governing the operation of the call switch of said link, thereby to extend the call from said one operator position, means at said operator position for completing the telephone apparatus thereat and the first and the second branches of said link, and means under the control of an operator at any one of said operator positions to complete a communication connection between the first and the second branches of said link independent of said one operator position.
22. In a telephone system, a plurality of lines, a plurality of links each including a first branch provided with an answer switch having access to said lines and a second branch provided with a call switch, means controlled by the presence of calls on said lines for assigning said links for use in a predetermined order and for causing the answer switches of said assigned links to seize said lines having calls thereon, thereby to extend the calls on said lines to said assigned links, a plurality of operator positions each including telephone apparatus, a storage unit, means for routing the calls on said assigned links to idle ones of said operator positions to be answered when one of said operator positions is idle, means under the control of an operator at any one of said operator positions to which the call on said link is routed for governing the operation of the call switch of said link, thereby to extend the call from said one operator position, means at said operator position for completing the telephone apparatus thereat and the first and the second branches of said link, and means under the control of an operator at any one of said operator positions to complete a communication connection between the first and the second branches of said link independent of said one operator position.

said operator positions are idle, means for routing the calls on said assigned links to said storage unit to be stored when all of said operator positions are busy, means for routing the calls on said assigned links stored in said storage unit to idle ones of said operator positions to be answered when said operator positions become idle, means under the control of an operator at any one of said operator positions to which the call on an assigned one of said links is routed for governing the operation of the call switch of said one assigned link, thereby to extend the call from said one operator position, means at any one of said operator positions for completing a three-way communication connection including the telephone apparatus thereat and the first and the second branches of an assigned one of said links, and means under the control of an operator at any one of said operator positions for completing a communication connection between the first and the second branches of an assigned one of said links independent of said one operator position.

22. In a telephone system, a first group of lines, a second group of lines, a plurality of operator positions each including telephone apparatus, a plurality of links each including a first branch provided with an answer switch having access to said first group of lines and a second branch provided with a call switch having access to said second group of lines and a third branch provided with a finder switch having access to said operator positions, means including a link distributor for assigning said links in a predetermined order and for causing the answer switch of an assigned link to seize a calling line in said first group of lines, thereby to extend the call on said calling line to said assigned link, means including a position distributor for assigning said operator positions in a predetermined order and for causing the finder switch of said assigned link to seize an assigned operator position, thereby to extend the call on said assigned link to said assigned operator position, means under the control of an operator at said assigned operator position for causing the call switch of said assigned link to seize a called line in said second group of lines, thereby to extend the call on said assigned link to said called line, means at said assigned operator position for completing a three-way communication connection including the telephone apparatus thereat and the first and the second and the third branches of said assigned link, and means under the control of an operator at said assigned operator position for completing a communication connection between the first and the second branches of said assigned link independent of the third branch thereof.

23. In a telephone system, a calling line, a called line, a link including an answer switch having access to said calling line and a call switch having access to said called line, means for causing the answer switch of said link to seize said calling line, thereby to extend the call to said link, an operator position, a storage unit, means for routing a call on said link to said operator position to be answered when said operator position is idle, means for routing a call on said link to said storage unit to be stored when said operator position is busy, means for routing a call on said link stored in said storage unit to said operator position to be answered when said operator position becomes idle, call means operative under the control of an operator at said operator position to cause the call switch of said

link to seize said called line, thereby to complete a connection between said calling line and said called line including said operator position, transfer means operative under the control of an operator at said operator position to complete a connection between said calling line and said called line excluding said operator position, means under the joint control of said calling line and an operator at said operator position for releasing the connection prior to the operation of said call means, and means under the joint control of said calling line and said called line for releasing the connection subsequent to the operation of said transfer means.

24. In a telephone system, a calling line, a called line, a link including an answer switch having access to said calling line and a call switch having access to said called line, means for causing the answer switch of said link to seize said calling line, thereby to extend the call to said link, a plurality of operator positions, a storage unit, means for routing a call on said link to an idle one of said operator positions to be answered when one of said operator positions is idle, means for routing a call on said link to said storage unit to be stored when all of said operator positions are busy, means for routing a call on said link stored in said storage unit to an idle one of said operator positions to be answered when one of said operator positions becomes idle, call means at each one of said operator positions operative to cause the call switch of said link to seize said called line, thereby to complete a connection between said calling line and said called line including said one operator position, transfer means at each one of said operator positions operative to cause the completion of a connection between said calling line and said called line excluding said one operator position, means under the joint control of said calling line and an operator at any one of said operator positions to which a call on said link is routed for releasing the connection prior to the operation of the call means at said one operator position, and means under the joint control of said calling line and said called line for releasing the connection subsequent to the operation of the transfer means at the one of said operator positions to which the call on said link was routed.

25. In a telephone system, a plurality of calling lines, a plurality of called lines, a plurality of links each including an answer switch having access to said calling lines and a call switch having access to said called lines, means for assigning said links for use in a predetermined order and for causing the answer switches of said assigned links to seize said calling lines, thereby to extend the calls to said assigned links, a plurality of operator positions, a storage unit, means for routing the calls on said assigned links to idle ones of said operator positions to be answered when said operator positions are idle, means for routing the calls on said assigned links to said storage unit to be stored when all of said operator positions are busy, means for routing the calls on said assigned links stored in said storage unit to idle ones of said operator positions to be answered when said operator positions become idle, calling means at said operator positions operative to cause the call switches of said assigned links to seize said called lines, thereby to complete connections between said calling lines and said called lines including said operator positions, transfer means at said operator positions operative to cause the completion of connections be-

tween said calling lines and said called lines excluding said operator positions, means under the joint control of any one of said calling lines and an operator at any one of said operator positions to which a call on the corresponding one of said assigned links is routed for releasing the connection prior to the operation of the calling means at said one operator position, and means under the joint control of any one of said calling lines and the corresponding one of said called lines for releasing the connection subsequent to the operation of the transfer means at the one of said operator positions to which the call on the corresponding one of said assigned links was routed.

26. In a telephone system, a first group of lines, a second group of lines, a plurality of operator positions, a plurality of links each including an answer switch having access to said first group of lines and a call switch having access to said second group of lines and switching apparatus having access to said operator positions, means including a link distributor for assigning said links in a predetermined order and for causing the answer switch of an assigned link to seize a calling line in said first group of lines, thereby to extend the call on said calling line to said assigned link, means including a position distributor for assigning said operator positions in a predetermined order and for causing the switching apparatus of said assigned link to seize an assigned operator position, thereby to extend the call on said assigned link to said assigned operator position, call means operative under the control of an operator at said assigned operator position to cause the call switch of said assigned link to seize a called line in said second group of lines, thereby to extend the call on said assigned link to said called line, whereupon a connection is completed between said calling line and said called line including said assigned operator position, transfer means operative under the control of an operator at said assigned operator position to complete a connection between said calling line and said called line excluding said assigned operator position, means under the joint control of said calling line and an operator at said assigned operator position for releasing the connection prior to the operation of said call means, and means under the joint control of said calling line and said called line for releasing the connection subsequent to the operation of said transfer means.

27. In a telephone system, a plurality of lines, means for establishing a connection between two of said lines, thereby to route a call from one of said lines to the other of said lines, a storage unit, means for routing a recall upon said established connection to said storage unit to be stored, a plurality of operator positions, and means for routing a recall upon said established connection stored in said storage unit to an idle one of said operator positions to be answered.

28. In a telephone system, a plurality of lines, means for establishing a connection between two of said lines, thereby to route a call from one of said lines to the other of said lines, a plurality of operator positions, a storage unit, means for routing a recall upon said established connection to an idle one of said operator positions to be answered when one of said operator positions is idle, means for routing a recall upon said established connection to said storage unit to be stored when all of said operator positions are busy, and means for routing a recall upon said established

connection stored in said storage unit to an idle one of said operator positions to be answered when one of said operator positions becomes idle.

29. In a telephone system, a plurality of lines, a plurality of operator positions, a storage unit, means for routing a call upon any one of said lines to said storage unit to be stored, means for routing a call upon said one line stored in said storage unit to an idle one of said operator positions to be answered, means for routing a call from said one operator position to another of said lines, means for establishing a connection between said one line and said other line independent of said one operator position, thereby to route a call from said one line to said other line, means for routing a recall upon said established connection to said storage unit to be stored, and means for routing a recall upon said established connection stored in said storage unit to an idle one of said operator positions to be answered.

30. In a telephone system, a plurality of lines, a plurality of operator positions, a storage unit, means for routing a call upon any one of said lines to an idle one of said operator positions to be answered when one of said operator positions is idle, means for routing a call upon said one line to said storage unit to be stored when all of said operator positions are busy, means for routing a call upon said one line stored in said storage unit to an idle one of said operator positions to be answered when one of said operator positions becomes idle, means for routing a call from said one operator position to another of said lines, means for establishing a connection between said one line and said other line independent of said one operator position, thereby to route a call from said one line to said other line, means for routing a recall upon said established connection to an idle one of said operator positions to be answered when one of said operator positions is idle, means for routing a recall upon said established connection to said storage unit to be stored when all of said operator positions are busy, and means for routing a recall upon said established connection stored in said storage unit to an idle one of said operator positions to be answered when one of said operator positions becomes idle.

31. In a telephone system, a calling line, a called line, a link including an answer switch having access to said calling line and a call switch having access to said called line, means for causing the answer switch of said link to seize said calling line, thereby to extend the call to said link, a plurality of operator positions, switching apparatus having access to said operator positions, means for causing said switching apparatus to route a call on said link to an idle one of said operator positions to be answered, call means operative under the control of an operator at said one operator position to cause the call switch of said link to seize said called line, thereby to complete a connection between said calling line and said called line including said one operator position, transfer means operative under the control of an operator at said one operator position to complete a connection between said calling line and said called line excluding said one operator position, and means operative subsequent to the operation of said transfer means to cause said switching apparatus to route a recall on said link to an idle one of said operator positions to be answered.

32. In a telephone system, a calling line, a called line, a link including an answer switch having access to said calling line and a call switch

having access to said called line, means for causing the answer switch of said link to seize said calling line, thereby to extend the call to said link, a plurality of operator positions, means including a position distributor for assigning said operator positions in a predetermined order, switching apparatus having access to said operator positions, means for causing said switching apparatus to route a call on said link to an assigned operator position to be answered, call means operative under the control of an operator at said assigned operator position to cause the call switch of said link to seize said called line, thereby to complete a connection between said calling line and said called line including said assigned operator position, transfer means operative under the control of an operator at said assigned operator position to complete a connection between said calling line and said called line excluding said assigned operator position, and means operative subsequent to the operation of said transfer means to cause said switching apparatus to route a recall on said link to an assigned operator position to be answered.

33. In a telephone system, a calling line, a called line, a link including an answer switch having access to said calling line and a call switch having access to said called line, means for causing the answer switch of said link to seize said calling line, thereby to extend the call to said link, a plurality of operator positions, switching apparatus having access to said operator positions, means for causing said switching apparatus to route a call on said link to an idle one of said operator positions to be answered, call means operative under the control of an operator at said one operator position to cause the call switch of said link to seize said called line, thereby to complete a connection between said calling line and said called line including said one operator position, transfer means operative under the control of an operator at said one operator position to complete a connection between said calling line and said called line excluding said one operator position, and means controlled over said called line subsequent to the operation of said transfer means to cause said switching apparatus to route a recall on said link to an idle one of said operator positions to be answered.

34. In a telephone system, a calling line, a called line, means for establishing a connection between said lines, a plurality of operator positions, and means controllable over said established connection for positively selecting an idle one of said operator positions to supervise said established connection.

35. In a telephone system, a calling line, a called line, means for establishing a connection between said lines, a plurality of operator positions, means for assigning said operator positions in a predetermined order, and means controllable over said established connection for selecting an assigned operator position to supervise said established connection.

36. In a telephone system, a plurality of lines, means for establishing a connection between two of said lines, thereby to extend a call from one of said lines to the other of said lines, a plurality of operator positions, and means responsive to a recall upon said established connection for positively selecting an idle one of said operator positions to answer the recall upon said established connection.

37. In a telephone system, a calling line, a called line, a plurality of operator positions,

means for establishing a connection between said calling line and an idle one of said operator positions, means for establishing a connection between said one operator position and said called line, thereby to complete an established connection between said calling line and said called line including said one operator position, means for establishing a connection between said calling line and said called line excluding said one operator position, and means controllable over said last-mentioned established connection for positively selecting an idle one of said operator positions to supervise said last-mentioned established connection.

38. In a telephone system, a calling line, a called line, a plurality of operator positions, means for assigning said operator positions in a predetermined order, means for establishing a connection between said calling line and an assigned operator position, means for establishing a connection between said assigned operator position and said called line, thereby to complete an established connection between said calling line and said called line including said assigned operator position, means for establishing a connection between said calling line and said called line excluding said assigned operator position, and means controllable over said last-mentioned established connection for selecting an assigned operator position to supervise said last-mentioned established connection.

39. In a telephone system, a plurality of lines, a plurality of operator positions, means for establishing a connection between any one of said lines and an idle one of said operator positions, thereby to extend a call from said one line to said one operator position to be answered, means for establishing a connection between said one operator position and another of said lines, thereby to extend a call from said one operator position to said other line, means for establishing a connection between said one line and said other line independent of said one operator position, thereby to extend a call from said one line to said other line, and means responsive to a recall upon said last-mentioned established connection for positively selecting an idle one of said operator positions to answer the recall upon said last-mentioned established connection.

40. In a telephone system, a plurality of operator positions, a plurality of trunks, a storage unit of limited storage capacity, a conservator of unlimited conservation capacity, means for routing calls on said trunks to said operator positions to be answered when said operator positions are idle, means for routing calls on said trunks to said storage unit to be stored when all of said operator positions are busy, means for routing calls on said trunks stored in said storage unit to said operator positions to be answered when said operator positions become idle, means for routing calls on said trunks to said conservator to be conserved when the storage capacity of said storage unit is exhausted, and means for routing calls on said trunks conserved in said conservator to said storage unit to be stored when the storage capacity of said storage unit is replenished.

41. In a telephone system, a plurality of lines, a link including an automatic switch having access to said lines, means controlled by the presence of a call on any one of said lines for causing said switch to seize said one line, thereby to extend the call to said link, an operator position, a storage unit, means for routing a call on said link to said operator position to be answered

when said operator position is idle, means for routing a call on said link to said storage unit to be stored when said operator position is busy, means for routing a call on said link stored in said storage unit to said operator position to be answered when said operator position becomes idle, means controlled when the call on said link is routed to said operator position or to said storage unit for preventing the release of said switch, and means under the control of an operator at said operator position for releasing said switch after the call on said link is routed to said operator position.

42. In a telephone system, a plurality of lines, a link including an automatic switch having access to said lines, means controlled by the presence of a call on any one of said lines for causing said switch to seize said one line, thereby to extend the call to said link, an operator position, a storage unit of limited storage capacity, a conservator of unlimited conservation capacity, means for routing a call on said link to said operator position to be answered when said operator position is idle, means for routing a call on said link to said storage unit to be stored when said operator position is busy, means for routing a call on said link stored in said storage unit to said operator position to be answered when said operator position becomes idle, means for routing a call on said link to said conservator to be conserved when the storage capacity of said storage unit is exhausted, means for routing a call on said link conserved in said conservator to said storage unit to be stored when the storage capacity of said storage unit is replenished, means controlled when the call on said link is routed to said operator position or to said storage unit or to said conservator for preventing the release of said switch, and means under the control of an operator at said operator position for releasing said switch after the call on said link is routed to said operator position.

43. In a telephone system, a plurality of lines, a link including an automatic switch having access to said lines, means controlled by the presence of a call on any one of said lines for causing said switch to seize said one line, thereby to extend the call to said link, a plurality of operator positions, a storage unit, means for routing a call on said link to an idle one of said operator positions to be answered when one of said operator positions is idle, means for routing a call on said link to said storage unit to be stored when all of said operator positions are busy, means for routing a call on said link stored in said storage unit to an idle one of said operator positions to be answered when one of said operator positions becomes idle, means controlled when the call on said link is routed to an idle one of said operator positions or to said storage unit for preventing the release of said switch, and means under the control of an operator at any one of said operator positions to which the call on said link is routed for releasing said switch.

44. In a telephone system, a plurality of lines, a plurality of links each including an automatic switch having access to said lines, means controlled by the presence of calls on said lines for assigning said links for use in a predetermined order and for causing the switches of said assigned links to seize said lines having calls thereon, thereby to extend the calls on said lines to said assigned links, a plurality of operator positions, a storage unit, means for routing the calls on said assigned links to idle ones of said oper-

ator positions to be answered when said operator positions are idle, means for routing the calls on said assigned links to said storage unit to be stored when all of said operator positions are busy, means for routing the calls on said assigned links stored in said storage unit to idle ones of said operator positions to be answered when said operator positions become idle, means controlled when the call on any one of said assigned links is routed to an idle one of said operator positions or to said storage unit for preventing the release of the switch of said one assigned link, and means under the control of an operator at any one of said operator positions to which the call on any one of said assigned links is routed for releasing the switch of said one assigned link.

45. In a telephone system, an operator position, a storage unit, a plurality of trunks, switching apparatus having access to said operator position and to said storage unit, means controlled when said operator position is idle for causing said switching apparatus to route calls on said trunks directly to said operator position to be answered independently of said storage unit, means controlled only when said operator position is busy for causing said switching apparatus to route calls on said trunks directly to said storage unit to be stored, means controlled when said operator position becomes idle for causing said switching apparatus to route any calls on said trunks stored in said storage unit to said operator position to be answered, and means including a storage distributor for controlling the order in which calls on said trunks stored in said storage unit are routed by said switching apparatus to said operator position.

46. In a telephone system, an operator position, a storage unit, a plurality of trunks, switching apparatus having access to said operator position and to said storage unit, means controlled when said operator position is idle for causing said switching apparatus to route calls on said trunks directly to said operator position to be answered independently of said storage unit, means controlled only when said operator position is busy for causing said switching apparatus to route calls on said trunks directly to said storage unit to be stored, means controlled when said operator position becomes idle for causing said switching apparatus to route any calls on said trunks stored in said storage unit to said operator position to be answered, and means including a storage distributor for causing said switching apparatus to route the calls on said trunks stored in said storage unit to said operator position in the same predetermined order that the calls on said trunks were stored in said storage unit.

47. In a telephone system, a plurality of operator positions, a storage unit, a plurality of trunks, switching apparatus having access to said operator positions and to said storage unit, means for causing said switching apparatus to route calls on said trunks directly to said operator positions to be answered independently of said storage unit when said operator positions are idle, means for causing said switching apparatus to route calls on said trunks directly to said storage unit to be stored only when all of said operator positions are busy, means for causing said switching apparatus to route any calls on said trunks stored in said storage unit to said operator positions to be answered as said operator positions become idle, and means including a storage distributor for controlling the order in which calls on said trunks stored in said storage unit are routed by

said switching apparatus to said operator positions.

48. In a telephone system, a plurality of operator positions, a storage unit, a plurality of trunks, switching apparatus having access to said operator positions and to said storage unit, means for causing said switching apparatus to route calls on said trunks directly to selected ones of said operator positions to be answered independently of said storage unit, means for causing said switching apparatus to route calls on said trunks directly to said storage unit to be stored only when there is no selected operator position, means for causing said switching apparatus to route any calls on said trunks stored in said storage unit to selected ones of said operator positions to be answered as said operator positions are selected, and means including a position distributor for selecting in a predetermined order said operator positions.

49. In a telephone system, a plurality of operator positions, a storage unit, a plurality of trunks, switching apparatus having access to said operator positions and to said storage unit, a position distributor, means for causing said position distributor to select an idle operator position, means controlled when a selected operator position is rendered busy for causing said position distributor to select another idle operator position, means controlled when a call is routed to an operator position to be answered for rendering busy the operator position, means controlled after a call routed to an operator position is answered thereat for rendering idle the operator position, means for causing said switching apparatus to route a call on any one of said trunks directly to a selected operator position independently of said storage unit, means for causing said switching apparatus to route a call on any one of said trunks stored in said storage unit to a selected operator position.

50. In a telephone system, a plurality of operator positions, a storage unit, a plurality of trunks, switching apparatus having access to said operator positions and to said storage unit, a position distributor operative automatically to test for an idle operator position, means for arresting operation of said position distributor when an idle operator position is tested and for causing said position distributor to select the operator position tested idle, means controlled when a selected operator position is rendered busy for initiating further operation of said position distributor, means controlled when a call is routed to an operator position to be answered for rendering busy the operator position, means controlled after a call routed to an operator position is answered thereat for rendering idle the operator position, means for causing said switching apparatus to route a call on any one of said trunks directly to a selected operator position independently of said storage unit, means for causing said switching apparatus to route a call on any one of said trunks directly to said storage unit to be stored only when there is no selected operator position, and means for causing said switching apparatus to route a call on any one of said trunks stored in said storage unit to a selected operator position.

51. In a telephone system, a plurality of operator positions, a storage unit, a plurality of trunks,

a plurality of finder switches individually associated with said trunks, each of said finder switches having access to said storage unit, means including said finder switches for routing calls on said trunks to said storage unit to be stored, switching apparatus for routing calls on said trunks stored in said storage unit to said operator positions to be answered, whereby a call on any one of said trunks stored in said storage unit may be routed to any one of said operator positions to be answered, and means including a storage distributor for controlling the order in which calls on said trunks stored in said storage unit are routed by said switching apparatus to said operator positions.

52. In a telephone system, a plurality of operator positions, a storage unit, a plurality of trunks, a plurality of finder switches individually associated with said trunks, each of said finder switches having access to said storage unit, means including said finder switches for routing calls on said trunks to said storage unit to be stored when all of said operator positions are busy, switching apparatus selectively operative to route calls on said trunks directly to idle ones of said operator positions to be answered when there are no calls on said trunks stored in said storage unit and to route calls on said trunks stored in said storage unit to idle ones of said operator positions to be answered when there are calls on said trunks stored in said storage unit, means for selectively controlling the operation of said switching apparatus, and means including a storage distributor for controlling the order in which calls on said trunks stored in said storage unit are routed by said switching apparatus to said operator positions.

53. In a telephone system, a plurality of operator positions, a storage unit, a plurality of trunks, a plurality of finder switches individually associated with said trunks, each of said finder switches having access to said operator positions and to said storage unit, means controlled when all of said operator positions are busy for causing said finder switches to route calls on said trunks to said storage unit to be stored, means controlled when there are no calls on said trunks stored in said storage unit for causing said finder switches to route calls on said trunks directly to idle ones of said operator positions to be answered, means controlled when there are calls on said trunks stored in said storage unit for causing said finder switches to route calls on said trunks stored in said storage unit to idle ones of said operator positions to be answered, and means including a storage distributor for controlling the order in which calls on said trunks stored in said storage unit are routed by said finder switches to said operator positions.

54. In a telephone system, a plurality of operator positions, a storage unit, a plurality of trunks, a plurality of finder switches individually associated with said trunks, each of said finder switches having access to said storage unit, means including said finder switches for routing calls on said trunks to said storage unit to be stored, switching apparatus for routing calls on said trunks stored in said storage unit to selected ones of said operator positions to be answered, whereby a call on any one of said trunks stored in said storage unit may be routed to any one of said operator positions to be answered, means including a position distributor for selecting said operator positions in a predetermined order, and

means including a storage distributor for controlling the order in which calls on said trunks stored in said storage unit are routed by said switching apparatus to selected ones of said operator positions.

55. In a telephone system, a plurality of operator positions, a storage unit, a plurality of trunks, a plurality of finder switches individually associated with said trunks, each of said finder switches having access to said storage unit, means including said finder switches for routing calls on said trunks to said storage unit to be stored, means commonly associated with said operator positions for indicating the total number of calls on said trunks stored in said storage unit, switching apparatus for routing calls on said trunks stored in said storage unit to said operator positions to be answered, whereby a call on any one of said trunks stored in said storage unit may be routed to any one of said operator positions to be answered, and means including a storage distributor for controlling the order in which calls on said trunks stored in said storage unit are routed by said switching apparatus to said operator positions.

56. In a telephone system, a plurality of operator positions, a storage unit having a number of storage settings, a plurality of trunks, a plurality of finder switches individually associated with said trunks, each of said finder switches having a number of settings individually corresponding to the storage settings of said storage unit, means controlled when there are calls on said trunks for causing operation of the associated finder switches to different settings, thereby to store the calls on said trunks in the different storage settings of said storage unit, switching apparatus for routing the calls on said trunks stored in the storage settings of said storage unit to said operator positions to be answered, and means governed in accordance with the different settings of said finder switches for controlling the order in which the calls on said trunks stored in the storage settings of said storage unit are routed by said switching apparatus to said operator positions.

57. In a telephone system, a plurality of operator positions, a storage unit having a number of storage settings, a plurality of trunks, a plurality of finder switches individually associated with said trunks, each of said finder switches having a number of settings individually corresponding to the storage settings of said storage unit, means controlled when there are calls on said trunks for causing operation of the associated finder switches to different settings, thereby to store the calls on said trunks in the different storage settings of said storage unit in a predetermined order, switching apparatus for routing the calls on said trunks stored in the storage settings of said storage unit to said operator positions to be answered, and means governed in accordance with the different settings of said finder switches for causing the calls on said trunks stored in the storage settings of said storage unit to be routed by said switching apparatus to said operator positions in the same predetermined order as the calls on said trunks were stored in the storage settings of said storage unit.

58. In a telephone system, a plurality of operator positions, a storage unit having a number of storage settings, a storage distributor, a plurality of trunks, a plurality of finder switches individually associated with said trunks, each of said finder switches having a number of settings

individually corresponding to the storage settings of said storage unit, means controlled when there are calls on said trunks for initiating operation of the associated finder switches,

5 means controlled by said storage distributor for arresting operation of said finder switches in different settings, whereby the calls on said trunks are stored in the different storage settings of said storage unit, switching apparatus 10 for routing the calls on said trunks stored in the storage settings of said storage unit to said operator positions to be answered, and means governed in accordance with the different settings of said finder switches for controlling the order in which the calls on said trunks stored in the storage settings of said storage unit are routed by said switching apparatus to said operator positions.

59. In a telephone system, an operator position, a storage unit having a number of storage settings, a plurality of trunks, a plurality of finder switches individually associated with said trunks, each of said finder switches having a number of settings individually corresponding

20 to the storage settings of said storage unit, means controlled when there are calls on said trunks for causing operation of the associated finder switches to different settings, thereby to store the calls on said trunks in the different

30 storage settings of said storage unit, switching apparatus operative to route the call on the trunk stored in the first storage setting of said storage unit to said operator position to be answered, means for reoperating away from its first setting the finder switch operated to its first setting, means controlled by the reoperation of said last-mentioned finder switch for operating said switching apparatus, and means controlled by the reoperation of said last-mentioned finder switch for reoperating one setting each operated finder switch, thereby to advance each operated finder switch one setting toward its first setting.

60. In a telephone system, an operator position, a storage unit having a number of storage settings, a storage distributor, a plurality of

45 trunks, a plurality of finder switches individually associated with said trunks, each of said finder switches having a number of settings individually corresponding to the storage settings 50 of said storage unit, means for extending calls to said trunks, means controlled when successive calls are extended to first and second of said trunks for successively initiating operation of the associated first and second finder switches,

55 means controlled by said storage distributor for arresting operation of said first and second finder switches respectively in their first and second settings, thereby to store the calls on said first and second trunks respectively in the first and second storage settings of said storage unit,

60 switching apparatus operative to route the call on the trunk stored in the first storage setting of said storage unit to said operator position to be answered, means for reoperating away from its first setting said first finder switch, means controlled by the reoperation of said first finder switch for operating said switching apparatus, and means controlled by the reoperation of said first finder switch for reoperating one setting said second finder switch, thereby to advance said second finder switch to its first setting.

61. In a telephone system, an operator position, a storage unit including a number of storage relays, operating circuits for said storage

relays, a plurality of trunks, a plurality of finder switches individually associated with said trunks, each of said finder switches having a number of positions individually corresponding to the operating circuits of said storage relays, means for extending calls to said trunks, means controlled when successive calls are extended to first and second of said trunks for successively initiating operation of the associated first and second finder switches, means controlled when said first finder switch is operated to its first position for arresting operation of said first finder switch and for completing the operating circuit of a first of said storage relays, thereby to store the call on said first trunk in said storage unit, means controlled by the operation of said first storage relay for preparing the operating circuit of a second of said storage relays, means controlled when said second finder switch is operated to its second position for arresting operation of said second finder switch and for completing the operating circuit of said second storage relay, thereby to store the call on said second trunk in said storage unit, switching apparatus operative to route the calls on said trunks to said operator position to be answered, means for interrupting the operating circuit of said first storage relay and for causing reoperation of said first finder switch away from its first position, means controlled by the reoperation of said first finder switch for causing said switching apparatus to route the call on said first trunk to said operator position to be answered, and means controlled by the restoration of said first storage relay for interrupting the operating circuit of said second storage relay and for causing reoperation of said second finder switch from its second position to its first position, thereby to cause reoperation of said second finder switch to be arrested and to cause reoperation of said first storage relay.

62. In a telephone system, a plurality of operator positions, a storage unit having a number of storage settings, a plurality of trunks, a plurality of finder switches individually associated with said trunks, each of said finder switches having a number of settings individually corresponding to the storage settings of said storage unit, means controlled when there are calls on said trunks and all of said operator positions are busy for causing operation of the associated finder switches to different settings, thereby to store the calls on said trunks in the different storage settings of said storage unit, switching apparatus operative in a first manner to route the calls on said trunks directly to idle ones of said operator positions to be answered and operative in a second manner to route the calls on said trunks stored in the storage settings of said storage unit to idle ones of said operator positions to be answered, means controlled when there are no calls on said trunks stored in said storage unit for causing operation of said switching apparatus in said first manner and controlled when there are calls on said trunks stored in said storage unit for causing operation of said switching apparatus in said second manner, and means governed in accordance with the different settings of said finder switches when said switching apparatus is operated in said second manner for controlling the order in which the calls on said trunks stored in the storage settings of said storage unit are routed by said switching apparatus to said operator positions.

63. In a telephone system, a plurality of op-

erator positions, a storage unit having a number of storage settings, a plurality of trunks, a plurality of finder switches individually associated with said trunks, each of said finder switches having a first number of settings individually corresponding to said operator positions and a second number of settings individually corresponding to the storage settings of said storage unit, means controlled when all of said operator positions are busy for causing the finder switches associated with said trunks having calls thereon to be operated to different ones of said second settings, thereby to store the calls on said trunks in the different storage settings of said storage unit, means controlled when there are no calls on said trunks stored in said storage unit for causing the finder switches associated with said trunks having calls thereon to be operated to different ones of said first settings corresponding to idle ones of said operator positions, thereby to route the calls on said trunks to said operator positions to be answered, means controlled when there are calls on said trunks stored in the storage settings of said storage unit for causing the finder switches associated with said trunks to be reoperated from the different ones of said second settings to different ones of said first settings corresponding to idle ones of said operator positions, thereby to route the calls stored in said storage unit to idle ones of said operator positions to be answered, and means governed in accordance with the different ones of said second settings of said finder switches for controlling the order of reoperation of said finder switches.

64. In a telephone system, a first group of lines, a second group of lines, a plurality of links each including a first branch provided with an answer switch having access to said first group of lines and a second branch provided with a call switch having access to said second group of lines, means including a link distributor for assigning said links in a predetermined order and for causing the answer switch of an assigned link to seize a calling line in said first group of lines, thereby to extend the call on said calling line to said assigned link, an operator position, a trunk extending to said operator position and including first and second circuits interconnected at said operator position, switching apparatus for connecting the first and the second branches of said assigned link respectively to the first and second circuits of said trunk, thereby to extend the call on said assigned link to said operator position, means under the control of an operator at said operator position for causing the call switch of said assigned link to seize a called line in said second group of lines, thereby to extend the call on said assigned link to said called line, means at said operator position for completing a three-way communication connection by way of said trunk including said operator position and the first and the second branches of said assigned link, and means under the control of an operator at said operator position for completing a communication connection between the first and the second branches of said assigned link independent of said trunk.

65. In a telephone system, a first group of lines, a second group of lines, a plurality of links each including a first branch provided with an answer switch having access to said first group of lines and a second branch provided with a call switch having access to said second group of lines, means including a link distributor for assigning said links in a predetermined order and for causing

the answer switch of an assigned link to seize a calling line in said first group of lines, thereby to extend the call on said calling line to said assigned link, a plurality of operator positions, a plurality of trunks individually extending to said operator positions, each of said trunks including first and second circuits interconnected at the associated operator position, means including a position distributor for assigning said operator positions in a predetermined order, switching apparatus for connecting the first and the second branches of said assigned link respectively to the first and the second circuits of the trunk extending to an assigned operator position, thereby to extend the call on said assigned link to said assigned operator position, means under the control of an operator at said assigned operator position for causing the call switch of said assigned link to seize a called line in said second group of lines, thereby to extend the call on said assigned link to said called line, means at said assigned operator position for completing a three-way communication connection by way of the associated trunk including said assigned operator position and the first and the second branches of said assigned link, and means under the control of an operator at said assigned operator position for completing a communication connection between the first and the second branches of said assigned link independent of the associated trunk.

66. In a telephone system, an operator position, a plurality of trunks, a storage unit of limited storage capacity, a conservator of unlimited conservation capacity, means for routing calls on said trunks to said operator position to be answered when said operator position is idle, means for routing calls on said trunks to said storage unit to be stored when said operator position is busy, means for routing calls on said trunks stored in said storage unit to said operator position to be answered when said operator position becomes idle, means for routing calls on said trunks to said conservator to be conserved when the storage capacity of said storage unit is exhausted, and means for routing calls on said trunks conserved in said conservator to said storage unit to be stored when the storage capacity of said storage unit is replenished.

67. In a telephone system, an operator position, a storage unit having a number of storage settings, a plurality of trunks, a plurality of finder switches individually associated with said trunks, each of said finder switches having a number of settings individually corresponding to the storage settings of said storage unit, means controlled when there are calls on said trunks for causing operation of the associated finder switches to different settings, thereby to store the calls on said trunks in the different storage settings of said storage unit, switching apparatus for routing the calls on said trunks stored in the storage settings of said storage unit to said operator position to be answered, and means governed in accordance with the different settings of said finder switches for controlling the order in which the calls on said trunks stored in the storage settings of said storage unit are routed by said switching apparatus to said operator position.

68. In a telephone system, a telephone station, an operator position, a trunk extending to said operator position, an automatic switch train controllable from said telephone station to route a connection over said trunk to said operator position when said trunk is idle, a call storage cir-

cuit, said automatic switch train being operative to route said connection to said call storage circuit when said trunk is busy, means included in said call storage circuit for holding said switch train operated after the release of the connection at said telephone station, and means included in said circuit for extending the connection to said operator position over said trunk when said trunk becomes idle.

69. In a telephone system, a plurality of operator positions, a plurality of trunks, means for routing calls on said trunks to idle ones of said operator positions, call storage means for storing calls initiated on said trunks when all of said operator positions are busy and for releasing said calls from storage in the same order as they are stored, another operator position, and signal means at said other operator position for indicating the number of trunks occupied with calls which are in storage.

70. In a telephone system, a plurality of operator positions, a plurality of trunks, a call storage circuit associated with said trunks and including means for causing calls initiated on said trunks at a time when all of said operator positions are busy to be stored and means for causing said stored calls to be released from storage one by one as said operator positions become idle and means for routing any one of said calls released from storage to any idle one of said operator positions, and means comprising a slow-acting device operative in response to the release of one of said operator positions for causing a predetermined time delay between the release of said one operator position and the release of a call from storage.

71. In a telephone system, a plurality of operator positions, a plurality of trunks, a call storage circuit associated with said trunks and including a storage position distributor and a call release distributor, trunk circuits individual to said trunks and each including a storage position finder and means normally operative to route calls initiated on the associated trunk directly to idle ones of said operator positions, means including said storage position distributor and said storage position finders for storing in a predetermined order calls initiated on said trunks at a time when all of said operator positions are busy, and means including said storage position finders and said call release distributor and a slow-acting device controlled in accordance with the idle or busy condition of said operator positions for releasing the stored calls from storage in said predetermined order as said operator positions become idle, said slow-acting device being operative to cause a predetermined time delay between the release of an operator position and the release of a call from storage.

72. In a telephone system, a calling line, a called line, an operator position, telephone apparatus including a receiver at said operator position, automatic means responsive to the presence of a call on said calling line for completing a connection between said calling line and said telephone apparatus, means for completing a connection between said called line and said telephone apparatus, means for establishing a connection between said calling line and said called line independent of said telephone apparatus, and automatic means responsive to the presence of a recall upon said established connection for completing a connection between said established connection and said telephone apparatus, thereby to complete a three-way communication connec-

tion including said calling line and said called line and said telephone apparatus.

73. In a telephone system, a calling line, a called line, an operator position, telephone apparatus including a receiver at said operator position, means for establishing a connection between said calling line and said called line, and automatic means responsive to the presence of a recall

upon said established connection for completing a connection between said established connection and said telephone apparatus, thereby to complete a three-way communication connection including said calling line and said called line and said telephone apparatus.

THOMAS F. CROCKER.

CERTIFICATE OF CORRECTION.

Patent No. 2,249,459.

July 15, 1941.

THOMAS F. CROCKER.

It is hereby certified that error appears in the printed specification of the above numbered patent requiring correction as follows: Page 32, first column, line 61, claim 43, for "relatse" read --release--; and that the said Letters Patent should be read with this correction therein that the same may conform to the record of the case in the Patent Office.

Signed and sealed this 26th day of August, A. D. 1941.

Henry Van Arsdale,
Acting Commissioner of Patents.
